(57) **ABSTRACT**

An assistance apparatus includes wires, each of which couples an upper-body belt and one of left and right knee belts to each other, and a motor. To promote implementation of first assistance for a user in walking while carrying an object, the motor generates a tension greater than or equal to a third threshold value in a second wire and a fourth wire, a tension greater than or equal to the third threshold value in the second wire and a third wire, and a tension greater than or equal to the third threshold value in a first wire and the fourth wire. During execution of the operation described above, upon receipt of determination of implementation, to indicate that implementation of the first assistance is determined, the motor generates a tension greater than or equal to a fourth threshold value in the second wire and the fourth wire, a tension greater than or equal to the fourth threshold value in the second wire and the third wire, and a tension greater than or equal to the fourth threshold value in the first wire and the fourth wire.

IMPLEMENTATION OF CALIBRATION MODE**ASSISTANCE APPARATUS, ASSISTANCE METHOD, AND RECORDING MEDIUM****BACKGROUND****1. Technical Field**

The present disclosure relates to an assistance apparatus, an assistance method, and a recording medium for assisting a wearer in walking.

2. Description of the Related Art

For example, Japanese Unexamined Patent Application Publication No. 2009-213538 discloses an assistant outfit for assisting movements of joints of a user. The disclosed assistant outfit includes a thigh link to be attached to a thigh, a thigh restraint band that restrains movement of the thigh link, a lower-leg link to be attached to a lower leg, a lower-leg restraint band that restrains movement of the lower-leg link, and a knee assistant motor that changes the angle between the thigh link and the lower-leg link. Japanese Unexamined Patent Application Publication (Translation of PCT Application) No. 2016-528940 discloses a soft exosuit equipped with an actuator including an operating member. In the soft exosuit, activation of the actuator generates a moment around a joint of a user wearing the soft exosuit to assist the movement of the user.

SUMMARY

A need exists to provide assistance for movements of a user in different ways in accordance with the state of the user, such as whether the user is carrying an object such as luggage. A specific method for addressing this issue is not described in Japanese Unexamined Patent Application Publication No. 2009-213538 or Japanese Unexamined Patent Application Publication (Translation of PCT Application) No. 2016-528940.

One non-limiting and exemplary embodiment provides an assistance apparatus, an assistance method, and a recording medium that provide assistance in accordance with the state of a user.

In one general aspect, the techniques disclosed here feature an assistance apparatus including an upper-body belt to be worn on an upper half of a body of a user, a left knee belt to be worn on a left knee of the user, a right knee belt to be worn on a right knee of the user, a first wire that couples the upper-body belt and the left knee belt to each other on or above a front part of the body of the user, a second wire that couples the upper-body belt and the left knee belt to each other on or above a back part of the body of the user, a third wire that couples the upper-body belt and the right knee belt to each other on or above the front part of the body of the user, a fourth wire that couples the upper-body belt and the right knee belt to each other on or above the back part of the body of the user, at least one motor, and a control circuit. In first assistance for assisting the user in walking while carrying an object, the at least one motor generates (i) a tension greater than or equal to a first threshold value in the first wire during a first period, the first period being a period of 35% or more and 90% or less of a gait phase of a left leg of the user, (ii) a tension greater than or equal to the first threshold value in the second wire during a second period, the second period being a period of 0% or more and 25% or less and 65% or more and less than 100% of the gait phase of the left leg, (iii) a tension greater than

or equal to the first threshold value in the third wire during a third period, the third period being a period of 35% or more and 90% or less of a gait phase of a right leg of the user, (iv) a tension greater than or equal to the first threshold value in the fourth wire during a fourth period, the fourth period being a period of 0% or more and 25% or less and 65% or more and less than 100% of the gait phase of the right leg, (v) a tension less than a second threshold value in the first wire during a fifth period, the fifth period being a period of 0% or more and less than 100% of the gait phase of the left leg, except the first period, (vi) a tension greater than or equal to the second threshold value in the second wire during a sixth period, the sixth period being a period of 0% or more and less than 100% of the gait phase of the left leg, except the second period, (vii) a tension less than the second threshold value in the third wire during a seventh period, the seventh period being a period of 0% or more and less than 100% of the gait phase of the right leg, except the third period, and (viii) a tension greater than or equal to the second threshold value in the fourth wire during an eighth period, the eighth period being a period of 0% or more and less than 100% of the gait phase of the right leg, except the fourth period. Before implementation of the first assistance is determined, the at least one motor executes operations (a1) to (a3) of promoting implementation of the first assistance. In the operation (a1), the at least one motor generates a tension greater than or equal to a third threshold value in the second wire and the fourth wire. In the operation (a2), the at least one motor generates a tension greater than or equal to the third threshold value in the second wire and the third wire. In the operation (a3), the at least one motor generates a tension greater than or equal to the third threshold value in the first wire and the fourth wire. When the control circuit receives, during execution of the operations (a1) to (a3), determination that the first assistance is to be implemented, before the first assistance is implemented, the at least one motor executes operations (a4) to (a6) indicating that implementation of the first assistance is determined. In the operation (a4), the at least one motor generates a tension greater than or equal to a fourth threshold value in the second wire and the fourth wire. In the operation (a5), the at least one motor generates a tension greater than or equal to the fourth threshold value in the second wire and the third wire. In the operation (a6), the at least one motor generates a tension greater than or equal to the fourth threshold value in the first wire and the fourth wire. The first threshold value is larger than the second threshold value, and the fourth threshold value is larger than the third threshold value.

It should be noted that general or specific embodiments may be implemented as a system, an apparatus, a method, an integrated circuit, a computer program, a computer-readable recording medium such as a recording disk, or any selective combination thereof. The computer-readable recording medium includes a non-volatile recording medium such as a compact disc-read only memory (CD-ROM).

An assistance apparatus and so on according to aspects of the present disclosure can provide assistance in accordance with the state of a user. Additional benefits and advantages of the disclosed embodiments will become apparent from the specification and drawings. The benefits and/or advantages may be individually obtained by the various embodiments and features of the specification and drawings, which need not all be provided in order to obtain one or more of such benefits and/or advantages.

BRIEF DESCRIPTION OF THE DRAWINGS

FIG. 1 is a front view of a user wearing an assistance apparatus according to an embodiment, as viewed from the front;

FIG. 2 is a back view of the user wearing the assistance apparatus illustrated in FIG. 1;

FIG. 3 is a block diagram illustrating a functional configuration of the assistance apparatus according to the embodiment;

FIG. 4 is a diagram schematically illustrating the arrangement of constituent elements of the assistance apparatus illustrated in FIG. 1;

FIG. 5A is a diagram illustrating example motions of the right leg of the user, which are assisted by the assistance apparatus;

FIG. 5B is a diagram illustrating an example motion of the user to lift an object, which is assisted by the assistance apparatus;

FIG. 6A is a diagram illustrating a case where the assistance apparatus according to the embodiment assists flexion of the hip joint of the left leg of the user;

FIG. 6B is a diagram illustrating a case where the assistance apparatus according to the embodiment assists flexion of the hip joint of the right leg of the user;

FIG. 7A is a diagram illustrating a case where the assistance apparatus according to the embodiment assists extension of the hip joint of the left leg of the user;

FIG. 7B is a diagram illustrating a case where the assistance apparatus according to the embodiment assists extension of the hip joint of the right leg of the user;

FIG. 8 is a diagram illustrating an example of an input section of an input device included in the assistance apparatus according to the embodiment;

FIG. 9 is a diagram illustrating the arrangement of sensors and so on that are attached to the body of the user;

FIG. 10A is a diagram illustrating a relationship between contact sensors and the hands of the user;

FIG. 10B is a diagram illustrating an example of a signal of a contact sensor;

FIG. 11 is a diagram illustrating an example of a signal of a pressure-sensitive sensor;

FIG. 12 is a diagram illustrating an example of a signal of an acceleration sensor of an inertial measurement unit;

FIG. 13 is a perspective view of a user wearing an assistance apparatus according to a modification of the embodiment, as viewed obliquely from the front;

FIG. 14 is a front view of the user wearing the assistance apparatus illustrated in FIG. 13;

FIG. 15 is a back view of the user wearing the assistance apparatus illustrated in FIG. 13;

FIG. 16 is a diagram schematically illustrating the arrangement of constituent elements of the assistance apparatus illustrated in FIG. 13;

FIG. 17 is a block diagram illustrating a functional configuration of the assistance apparatus illustrated in FIG. 13;

FIG. 18 is a diagram illustrating a modification of the arrangement of wires in the assistance apparatus illustrated in FIG. 13;

FIG. 19 is a diagram illustrating a modification of the arrangement of wires in the assistance apparatus illustrated in FIG. 13;

FIG. 20 is a diagram illustrating a modification of the arrangement of wires in the assistance apparatus illustrated in FIG. 13;

FIG. 21 is a diagram illustrating a modification of the arrangement of wires in the assistance apparatus illustrated in FIG. 13;

FIG. 22A is a diagram illustrating a case where the assistance apparatus according to the modification assists flexion of the hip joint of the left leg of the user;

FIG. 22B is a diagram illustrating a case where the assistance apparatus according to the modification assists flexion of the hip joint of the right leg of the user;

FIG. 23A is a diagram illustrating a case where the assistance apparatus according to the modification assists extension of the hip joint of the left leg of the user;

FIG. 23B is a diagram illustrating a case where the assistance apparatus according to the modification assists extension of the hip joint of the right leg of the user;

FIG. 24 is a flowchart illustrating an example overall flow of an operation of the assistance apparatus according to the embodiment for assisting a user;

FIG. 25 is a diagram illustrating an example operation of the assistance apparatus according to the embodiment for assisting a user in walking forward while carrying no object;

FIG. 26 is a diagram illustrating an example operation of the assistance apparatus according to the embodiment for assisting a user in walking forward while carrying an object;

FIG. 27 is a diagram illustrating an example operation of the assistance apparatus according to the embodiment for assisting a stationary user in lifting an object;

FIG. 28 is a flowchart illustrating an example flow of a calibration operation performed by the assistance apparatus according to the embodiment;

FIG. 29A is a diagram illustrating an example operation of the assistance apparatus according to the embodiment for clarifying a normal walking mode;

FIG. 29B is a diagram illustrating an example operation of the assistance apparatus according to the embodiment for clarifying determination that the normal walking mode is to be implemented;

FIG. 30A is a diagram illustrating an example operation of the assistance apparatus according to the embodiment for clarifying an object transport walking mode;

FIG. 30B is a diagram illustrating an example operation of the assistance apparatus according to the embodiment for clarifying determination that the object transport walking mode is to be implemented;

FIG. 31A is a diagram illustrating an example operation of the assistance apparatus according to the embodiment for clarifying a lifting mode;

FIG. 31B is a diagram illustrating an example operation of the assistance apparatus according to the embodiment for clarifying determination that the lifting mode is to be implemented;

FIG. 32A is a diagram illustrating an example operation of the assistance apparatus according to the embodiment for clarifying a calibration mode; and

FIG. 32B is a diagram illustrating an example operation of the assistance apparatus according to the embodiment for clarifying determination that the calibration mode is to be implemented.

DETAILED DESCRIPTION

Underlying Knowledge Forming Basis of the Present Disclosure

The inventors of the present disclosure, or the present inventors, have studied the techniques described in Japanese Unexamined Patent Application Publication No. 2009-213538 (hereinafter referred to as "Patent Literature 1") and Japanese Unexamined Patent Application Publication (Translation of PCT Application) No. 2016-528940 (hereinafter referred to as "Patent Literature 2") mentioned in the "BACKGROUND" section and have examined techniques for supporting, or assisting, a user in walking. The present inventors have focused on changing states of a user, who is

a wearer of an assistance apparatus. For example, it is necessary that an assistance method for a user who is carrying an object such as luggage be different from an assistance method for a user who is carrying no object.

First, the present inventors have examined an assistance apparatus that assists a user in walking by applying forces generated by motors to the user through wires. To enable various kinds of assistance on the legs of a user, the present inventors have developed an assistance apparatus including wires, each of which is to be placed so as to extend across one of the front of the hip joint of the left leg of the user, the back of the hip joint of the left leg of the user, the front of the hip joint of the right leg of the user, and the back of the hip joint of the right leg of the user. The present inventors have further developed a configuration in which the wires are each coupled to an upper-body belt and a left knee belt or a right knee belt, which are to be attached to the body of the user, and are accordingly attached to the body of the user. Thus, the present inventors have devised an assistance apparatus having a simple configuration.

For example, Patent Literature 1 discloses an assistant outfit including a rod-shaped thigh link that is attached to a side portion of a thigh, and a rod-shaped lower-leg link that is attached to a side portion of a lower leg. The thigh link and the lower-leg link are coupled to a knee assistant motor. The knee assistant motor is driven to change the angle defined by the thigh link and the lower-leg link, and accordingly the assistant outfit assists flexion and extension of the knee of the user. The thigh link, the lower-leg link, and the knee assistant motor are attached to each of the side portion of the right leg of the user and the side portion of the left leg of the user, resulting in the assistant outfit disclosed in Patent Literature 1 having a structure that is large-scale and complicated for the user. Thus, the assistant outfit places a heavy burden on the user.

In Patent Literature 2, tension is applied to connection elements of the soft exosuit, which is worn on a part of the body of the user from the waist to a thigh and a lower leg, through a cable placed at the front part of the thigh of the user, thereby assisting flexion and extension of the knee of the user. In the soft exosuit disclosed in Patent Literature 2, the connection elements and so on, which are attached to the body of the user, are large-scale and complicated for the user. Thus, the soft exosuit places a heavy burden on the user.

In addition, none of Patent Literatures 1 and 2 discloses the details of a method for providing assistance in accordance with the state of a user. Accordingly, the present inventors have devised the following technique for providing assistance in accordance with the state of a user by using the assistance apparatus having a simple configuration described above.

An assistance apparatus according to an aspect of the present disclosure includes an upper-body belt to be worn on an upper half of a body of a user, a left knee belt to be worn on a left knee of the user, a right knee belt to be worn on a right knee of the user, a first wire that couples the upper-body belt and the left knee belt to each other on or above a front part of the body of the user, a second wire that couples the upper-body belt and the left knee belt to each other on or above a back part of the body of the user, a third wire that couples the upper-body belt and the right knee belt to each other on or above the front part of the body of the user, a fourth wire that couples the upper-body belt and the right knee belt to each other on or above the back part of the body of the user, at least one motor, and a control circuit. In first assistance for assisting the user in walking while carrying an

object, the at least one motor generates (i) a tension greater than or equal to a first threshold value in the first wire during a first period, the first period being a period of 35% or more and 90% or less of a gait phase of a left leg of the user, (ii) a tension greater than or equal to the first threshold value in the second wire during a second period, the second period being a period of 0% or more and 25% or less and 65% or more and less than 100% of the gait phase of the left leg, (iii) a tension greater than or equal to the first threshold value in the third wire during a third period, the third period being a period of 35% or more and 90% or less of a gait phase of a right leg of the user, (iv) a tension greater than or equal to the first threshold value in the fourth wire during a fourth period, the fourth period being a period of 0% or more and 25% or less and 65% or more and less than 100% of the gait phase of the right leg, (v) a tension less than a second threshold value in the first wire during a fifth period, the fifth period being a period of 0% or more and less than 100% of the gait phase of the left leg, except the first period, (vi) a tension greater than or equal to the second threshold value in the second wire during a sixth period, the sixth period being a period of 0% or more and less than 100% of the gait phase of the left leg, except the second period, (vii) a tension less than the second threshold value in the third wire during a seventh period, the seventh period being a period of 0% or more and less than 100% of the gait phase of the right leg, except the third period, and (viii) a tension greater than or equal to the second threshold value in the fourth wire during an eighth period, the eighth period being a period of 0% or more and less than 100% of the gait phase of the right leg, except the fourth period. Before implementation of the first assistance is determined, the at least one motor executes operations (a1) to (a3) of promoting implementation of the first assistance. In the operation (a1), the at least one motor generates a tension greater than or equal to a third threshold value in the second wire and the fourth wire. In the operation (a2), the at least one motor generates a tension greater than or equal to the third threshold value in the second wire and the third wire. In the operation (a3), the at least one motor generates a tension greater than or equal to the third threshold value in the first wire and the fourth wire. When the control circuit receives, during execution of the operations (a1) to (a3), determination that the first assistance is to be implemented, before the first assistance is implemented, the at least one motor executes operations (a4) to (a6) indicating that implementation of the first assistance is determined. In the operation (a4), the at least one motor generates a tension greater than or equal to a fourth threshold value in the second wire and the fourth wire. In the operation (a5), the at least one motor generates a tension greater than or equal to the fourth threshold value in the second wire and the third wire. In the operation (a6), the at least one motor generates a tension greater than or equal to the fourth threshold value in the first wire and the fourth wire. The first threshold value is larger than the second threshold value, and the fourth threshold value is larger than the third threshold value.

In the configuration described above, the tension generated in the first wire can apply an assistance force for flexion to the left leg of the user, and the tension generated in the third wire can apply an assistance force for flexion to the right leg of the user. The tension generated in the second wire can apply an assistance force for extension to the left leg of the user, and the tension generated in the fourth wire can apply an assistance force for extension to the right leg of the user. The assistance apparatus generates a tension greater than or equal to the first threshold value in the first wire during a first period in the gait phase of the left leg to

assist flexion of the left leg, and generates a tension greater than or equal to the first threshold value in the third wire during a third period in the gait phase of the right leg to assist flexion of the right leg, thereby assisting the user in walking. Further, the assistance apparatus sets the tension of the first wire to be less than the second threshold value during a fifth period in the gait phase of the left leg and sets the tension of the third wire to be less than the second threshold value during a seventh period in the gait phase of the right leg to reduce assistance for flexing or stop assistance for flexion, thereby reducing an influence on extension of the legs. Further, the assistance apparatus generates a tension greater than or equal to the first threshold value in the second wire during a second period in the gait phase of the left leg to assist extension of the left leg, and generates a tension greater than or equal to the first threshold value in the fourth wire during a fourth period in the gait phase of the right leg to assist extension of the right leg, thereby assisting the user in walking. Further, the assistance apparatus sets the tension of the second wire to be greater than or equal to the second threshold value during a sixth period in the gait phase of the left leg to assist extension of the left leg, and sets the tension of the fourth wire to be greater than or equal to the second threshold value during an eighth period in the gait phase of the right leg to assist extension of the right leg. This may keep the center of gravity of the body of the user, who is carrying an object, at the position in the upright posture of the user. Therefore, the assistance apparatus can assist a user in walking while carrying an object while keeping the user in a stable posture. That is, the assistance apparatus can provide assistance to a user in accordance with the state of the user.

Further, the assistance apparatus generates a tension greater than or equal to the third threshold value in three pairs of wires to promote implementation of the first assistance. Upon receipt of determination that the first assistance is to be implemented, the assistance apparatus generates a tension greater than or equal to a fourth threshold value larger than the third threshold value in the same three pairs of wires. Accordingly, the assistance apparatus promotes implementation of the first assistance in such a way that the user can experience bodily sensations, and notifies the user of determination of implementation of the first assistance in such a way that the user can experience stronger bodily sensations. This allows the user to intuitively distinctly recognize different kinds of information about the first assistance, which are presented by the assistance apparatus, through bodily sensations without viewing them on a screen or the like. The assistance apparatus thus allows a user who is unfamiliar with a complex operation to easily select and implement the first assistance. Accordingly, the assistance apparatus can provide assistance to a user in accordance with the state of the user.

The first threshold value may be a tension value that allows the user to recognize that the movement of a leg is promoted by a tension generated in a wire, and may be 40 newtons (N), for example. The second threshold value may be a tension value that is not perceivable by the user. The second threshold value may be a tension value that prevents a wire from loosening, and may be a value that is 0.2 to 0.4 times the first threshold value or 10 N, for example. The third threshold value may be a relatively small value that allows the user to clearly recognize a tension generated in a wire when the user is aware of the wire, but that keeps the load on the user low, and may be, for example, 20 N. The fourth threshold value may be a relatively large value that

allows the user to clearly recognize a tension generated in a wire without awareness of the wire and may be, for example, 40 N.

In the assistance apparatus according to the aspect of the present disclosure, the left leg may shift from a stance phase to a swing phase during the first period, the left leg may shift from the swing phase to the stance phase during the second period, the right leg may shift from the stance phase to the swing phase during the third period, and the right leg may shift from the swing phase to the stance phase during the fourth period.

In the configuration described above, the assistance apparatus assists flexion during the first period in which the left leg shifts from the stance phase to the swing phase, and assists flexion during the third period in which the right leg shifts from the stance phase to the swing phase. Thus, the assistance apparatus can effectively assist the user in walking. Further, the assistance apparatus assists extension during the second period in which the left leg shifts from the swing phase to the stance phase, and assists extension during the fourth period in which the right leg shifts from the swing phase to the stance phase. Thus, the assistance apparatus can effectively assist the user in walking.

In the assistance apparatus according to the aspect of the present disclosure, in the first assistance, the tension of the first wire in the fifth period may be less than the tension of the second wire in the sixth period, and the tension of the third wire in the seventh period may be less than the tension of the fourth wire in the eighth period.

In the configuration described above, the tension of the first wire in the fifth period during the gait phase of the left leg can be prevented from affecting assistance for extension with the tension of the second wire in the sixth period during the gait phase of the left leg. Further, the tension of the third wire in the seventh period during the gait phase of the right leg can be prevented from affecting assistance for extension with the tension of the fourth wire in the eighth period during the gait phase of the right leg. Thus, assistance with the center of gravity of the body of the user, who is carrying an object, being kept at the position in the upright posture of the user can be effectively achieved.

In the assistance apparatus according to the aspect of the present disclosure, in second assistance for assisting the user in walking while carrying no object, the at least one motor may generate (i) a tension less than the second threshold value in the first wire during the fifth period, (ii) a tension less than the second threshold value in the second wire during the sixth period, (iii) a tension less than the second threshold value in the third wire during the seventh period, and (iv) a tension less than the second threshold value in the fourth wire during the eighth period. The tension of the second wire in the sixth period during the second assistance may be less than the tension of the second wire in the sixth period during the first assistance, and the tension of the fourth wire in the eighth period during the second assistance may be less than the tension of the fourth wire in the eighth period during the first assistance. Before implementation of the second assistance is determined, the at least one motor may execute operations (b1) and (b2) of promoting implementation of the second assistance. In the operation (b1), the at least one motor may generate a tension greater than or equal to the third threshold value in the second wire and the third wire. In the operation (b2), the at least one motor may generate a tension greater than or equal to the third threshold value in the first wire and the fourth wire. When the control circuit receives, during execution of the operations (b1) and (b2), determination that the second assistance is to be

implemented, before the second assistance is implemented, the at least one motor may execute operations (b3) and (b4) indicating that implementation of the second assistance is determined. In the operation (b3), the at least one motor may generate a tension greater than or equal to the fourth threshold value in the second wire and the third wire. In the operation (b4), the at least one motor may generate a tension greater than or equal to the fourth threshold value in the first wire and the fourth wire.

In the configuration described above, the load imposed on the left leg by the tension of the first wire is reduced during a period other than the first period during which flexion of the left leg is assisted. The load imposed on the left leg by the tension of the second wire is reduced during a period other than the second period during which extension of the left leg is assisted. The load imposed on the right leg by the tension of the third wire is reduced during a period other than the third period during which flexion of the right leg is assisted. The load imposed on the right leg by the tension of the fourth wire is reduced during a period other than the fourth period during which extension of the right leg is assisted. Thus, a user, who is not carrying an object, can be assisted with reduced loads.

Further, the assistance apparatus generates a tension greater than or equal to the third threshold value in two pairs of wires to promote implementation of the second assistance. Upon receipt of determination that the second assistance is to be implemented, the assistance apparatus generates a tension greater than or equal to the fourth threshold value in the same two pairs of wires. Accordingly, the assistance apparatus promotes implementation of the second assistance in such a way that the user can experience bodily sensations, and notifies the user of determination of implementation of the second assistance in such a way that the user can experience stronger bodily sensations.

In the assistance apparatus according to the aspect of the present disclosure, in third assistance for assisting the user in lifting an object, the at least one motor may generate a tension greater than a fifth threshold value in the second wire and the fourth wire. The fifth threshold value may be larger than the first threshold value and the second threshold value. Before implementation of the third assistance is determined, the at least one motor may execute an operation (c1) of promoting implementation of the third assistance. In the operation (c1), the at least one motor may generate a tension greater than or equal to the third threshold value in the second wire and the fourth wire. When the control circuit receives, during execution of the operation (c1), determination that the third assistance is to be implemented, before the third assistance is implemented, the at least one motor may execute an operation (c2) indicating that implementation of the third assistance is determined. In the operation (c2), the at least one motor may generate a tension greater than or equal to the fourth threshold value in the second wire and the fourth wire.

In the configuration described above, when the user lifts an object, the assistance apparatus applies an assistance force via wire tension so as to allow extension of the left leg and the right leg. The assistance force allows the user to easily shift from the lean-forward posture to the upright posture when the user lifts an object. Further, the assistance apparatus generates a tension greater than or equal to the third threshold value in a pair of wires to promote implementation of the third assistance. Upon receipt of determination that the third assistance is to be implemented, the assistance apparatus generates a tension greater than or equal to the fourth threshold value in the same pair of wires.

Accordingly, the assistance apparatus promotes implementation of the third assistance in such a way that the user can experience bodily sensations, and notifies the user of determination of implementation of the third assistance in such a way that the user can experience stronger bodily sensations. In addition, since a tension greater than the fifth threshold value, a tension greater than or equal to the third threshold value, and a tension greater than or equal to the fourth threshold value are generated in the same wire during the third assistance and the operations (c1) and (c2), the user is able to readily recognize the operations (c1) and (c2) and the third assistance in association with each other.

In the assistance apparatus according to the aspect of the present disclosure, the at least one motor may include a first motor, a second motor, a third motor, and a fourth motor. The first wire may have a first end fixed to the left knee belt. The first wire may have a second end fixed to the first motor. The second wire may have a first end fixed to the left knee belt. The second wire may have a second end fixed to the second motor. The third wire may have a first end fixed to the right knee belt. The third wire may have a second end fixed to the third motor. The fourth wire may have a first end fixed to the right knee belt. The fourth wire may have a second end fixed to the fourth motor.

In the configuration described above, the assistance apparatus can separately control the tension of the first wire, the tension of the second wire, the tension of the third wire, and the tension of the fourth wire. Thus, the assistance apparatus can provide fine assistance.

The assistance apparatus according to the aspect of the present disclosure may further include a fifth wire that couples the upper-body belt and the left knee belt to each other and that extends on or above the front part of the body of the user in a direction crossing a direction in which the first wire extends, a sixth wire that couples the upper-body belt and the left knee belt to each other and that extends on or above the back part of the body of the user in a direction crossing a direction in which the second wire extends, a seventh wire that couples the upper-body belt and the right knee belt to each other and that extends on or above the front part of the body of the user in a direction crossing a direction in which the third wire extends, and an eighth wire that couples the upper-body belt and the right knee belt to each other and that extends on or above the back part of the body of the user in a direction crossing a direction in which the fourth wire extends. In the first assistance, the at least one motor may generate (i) a tension greater than or equal to the first threshold value in the first wire and the fifth wire during the first period, (ii) a tension greater than or equal to the first threshold value in the second wire and the sixth wire during the second period, (iii) a tension greater than or equal to the first threshold value in the third wire and the seventh wire during the third period, (iv) a tension greater than or equal to the first threshold value in the fourth wire and the eighth wire during the fourth period, (v) a tension less than the second threshold value in the first wire and the fifth wire during the fifth period, (vi) a tension greater than or equal to the second threshold value in the second wire and the sixth wire during the sixth period, (vii) a tension less than the second threshold value in the third wire and the seventh wire during the seventh period, and (viii) a tension greater than or equal to the second threshold value in the fourth wire and the eighth wire during the eighth period.

In the configuration described above, the tension generated in the first wire and the tension generated in the fifth wire can apply an assistance force for flexion to the left leg of the user. The tension generated in the second wire and the

11

tension generated in the sixth wire can apply an assistance force for extension to the left leg of the user. The tension generated in the third wire and the tension generated in the seventh wire can apply an assistance force for flexion to the right leg of the user. The tension generated in the fourth wire and the tension generated in the eighth wire can apply an assistance force for extension to the right leg of the user. Thus, the assistance apparatus including the first to eighth wires can provide assistance similar to that of the assistance apparatus including the first to fourth wires. In addition, the assistance apparatus including the first to eighth wires separately controls the tensions of the first to eighth wires, thereby providing more types of assistance. For example, the tension generated in the first wire and the tension generated in the fifth wire may be the same or different, and a different type of assistance can be provided in each case.

In the assistance apparatus according to the aspect of the present disclosure, a time point of 50% of the gait phase of the left leg may correspond to a time point of 0% of the gait phase of the right leg, and a time point of 50% of the gait phase of the right leg may correspond to a time point of 0% of the gait phase of the left leg.

The assistance apparatus according to the aspect of the present disclosure may further include a memory. The memory may store a program for controlling the at least one motor. The control circuit may control the at least one motor in accordance with the program.

The assistance apparatus according to the aspect of the present disclosure may further include a sensor that detects a gait cycle of the user. The control circuit may calculate the gait phase of the left leg and the gait phase of the right leg based on a sensor value of the sensor.

In the configuration described above, the assistance apparatus can assist the user in walking on the basis of a gait phase corresponding to a gait cycle of the user. Thus, the assistance apparatus can provide assistance based on actual user walking.

In the assistance apparatus according to the aspect of the present disclosure, in second assistance for assisting the user in walking while carrying no object, the at least one motor may generate (i) a tension less than the second threshold value in the first wire during the fifth period, (ii) a tension less than the second threshold value in the second wire during the sixth period, (iii) a tension less than the second threshold value in the third wire during the seventh period, and (iv) a tension less than the second threshold value in the fourth wire during the eighth period. The tension of the second wire in the sixth period during the second assistance may be less than the tension of the second wire in the sixth period during the first assistance, and the tension of the fourth wire in the eighth period during the second assistance may be less than the tension of the fourth wire in the eighth period during the first assistance. Before implementation of the second assistance is determined, the at least one motor may execute operations (b1) and (b2) of promoting implementation of the second assistance. In the operation (b1), the at least one motor may generate a tension greater than or equal to the third threshold value in the second wire and the third wire. In the operation (b2), the at least one motor may generate a tension greater than or equal to the third threshold value in the first wire and the fourth wire. When the control circuit receives, during execution of the operations (b1) and (b2), determination that the second assistance is to be implemented, before the second assistance is implemented, the at least one motor may execute operations (b3) and (b4) indicating that implementation of the second assistance is determined. In the operation (b3), the at least one motor may

12

generate a tension greater than or equal to the fourth threshold value in the second wire and the third wire. In the operation (b4), the at least one motor may generate a tension greater than or equal to the fourth threshold value in the first wire and the fourth wire. The assistance apparatus may further include an interface device. The control circuit may accept selection of an assistance method including at least one of the first assistance, the second assistance, or the third assistance via the interface device. The control circuit may control the at least one motor in accordance with the accepted assistance method.

In the configuration described above, the assistance apparatus enables selection of an assistance method desired by the user.

An assistance method according to another aspect of the present disclosure is an assistance method for assisting a movement of a user by using wires attached to a body of the user. The assistance method includes coupling, using a first wire among the wires, an upper-body belt and a left knee belt to each other on or above a front part of the body of the user, the upper-body belt being a belt to be worn on an upper half of the body of the user, the left knee belt being a belt to be worn on a left knee of the user; coupling, using a second wire among the wires, the upper-body belt and the left knee belt to each other on or above a back part of the body of the user; coupling, using a third wire among the wires, the upper-body belt and a right knee belt to each other on or above the front part of the body of the user, the right knee belt being a belt to be worn on a right knee of the user; coupling, using a fourth wire among the wires, the upper-body belt and the right knee belt to each other on or above the back part of the body of the user; in first assistance for assisting the user in walking while carrying an object, generating a tension greater than or equal to a first threshold value in the first wire during a first period, the first period being a period of 35% or more and 90% or less of a gait phase of a left leg of the user; generating a tension greater than or equal to the first threshold value in the second wire during a second period, the second period being a period of 0% or more and 25% or less and 65% or more and less than 100% of the gait phase of the left leg; generating a tension greater than or equal to the first threshold value in the third wire during a third period, the third period being a period of 35% or more and 90% or less of a gait phase of a right leg of the user; generating a tension greater than or equal to the first threshold value in the fourth wire during a fourth period, the fourth period being a period of 0% or more and 25% or less and 65% or more and less than 100% of the gait phase of the right leg; generating a tension less than a second threshold value in the first wire during a fifth period, the fifth period being a period of 0% or more and less than 100% of the gait phase of the left leg, except the first period; generating a tension greater than or equal to the second threshold value in the second wire during a sixth period, the sixth period being a period of 0% or more and less than 100% of the gait phase of the left leg, except the second period; generating a tension less than the second threshold value in the third wire during a seventh period, the seventh period being a period of 0% or more and less than 100% of the gait phase of the right leg, except the third period; generating a tension greater than or equal to the second threshold value in the fourth wire during an eighth period, the eighth period being a period of 0% or more and less than 100% of the gait phase of the right leg, except the fourth period; before determining that the first assistance is to be implemented, executing operations (a1) to (a3) of promoting implementation of the first assistance; in the operation (a1),

generating a tension greater than or equal to a third threshold value in the second wire and the fourth wire; in the operation (a2), generating a tension greater than or equal to the third threshold value in the second wire and the third wire; in the operation (a3), generating a tension greater than or equal to the third threshold value in the first wire and the fourth wire; when receiving, during execution of the operations (a1) to (a3), determination that the first assistance is to be implemented, before implementation of the first assistance, executing operations (a4) to (a6) indicating that implementation of the first assistance is determined; in the operation (a4), generating a tension greater than or equal to a fourth threshold value in the second wire and the fourth wire; in the operation (a5), generating a tension greater than or equal to the fourth threshold value in the second wire and the third wire; and in the operation (a6), generating a tension greater than or equal to the fourth threshold value in the first wire and the fourth wire. The first threshold value is larger than the second threshold value, and the fourth threshold value is larger than the third threshold value. The tension of the first wire, the tension of the second wire, the tension of the third wire, and the tension of the fourth wire are adjusted by a motor that is controlled by at least one control circuit. The assistance method according to the aspect described above can achieve advantages similar to those of the assistance apparatus according to the aspect of the present disclosure.

In the assistance method according to the aspect of the present disclosure, the left leg may shift from a stance phase to a swing phase during the first period, the left leg may shift from the swing phase to the stance phase during the second period, the right leg may shift from the stance phase to the swing phase during the third period, and the right leg may shift from the swing phase to the stance phase during the fourth period.

In the assistance method according to the aspect of the present disclosure, in the first assistance, the tension of the first wire in the fifth period may be less than the tension of the second wire in the sixth period, and the tension of the third wire in the seventh period may be less than the tension of the fourth wire in the eighth period.

The assistance method according to the aspect of the present disclosure may further include, in second assistance for assisting the user in walking while carrying no object, generating a tension less than the second threshold value in the first wire during the fifth period; generating a tension less than the second threshold value in the second wire during the sixth period; generating a tension less than the second threshold value in the third wire during the seventh period; generating a tension less than the second threshold value in the fourth wire during the eighth period, the tension of the second wire in the sixth period during the second assistance being less than the tension of the second wire in the sixth period during the first assistance, the tension of the fourth wire in the eighth period during the second assistance being less than the tension of the fourth wire in the eighth period during the first assistance; before determining that the second assistance is to be implemented, executing operations (b1) and (b2) of promoting implementation of the second assistance; in the operation (b1), generating a tension greater than or equal to the third threshold value in the second wire and the third wire; in the operation (b2), generating a tension greater than or equal to the third threshold value in the first wire and the fourth wire; when receiving, during execution of the operations (b1) and (b2), determination that the second assistance is to be implemented, before implementation of the second assistance, executing operations (b3) and (b4) indicating that implementation of the second assistance is determined; in the operation (b3), generating a tension greater than or equal to the fourth threshold value in the second wire and the third wire; and in the operation (b4), generating a tension greater than or equal to the fourth threshold value in the first wire and the fourth wire.

The assistance method according to the aspect of the present disclosure may further include, in third assistance for assisting the user in lifting an object, generating a tension greater than a fifth threshold value in the second wire and the fourth wire, the fifth threshold value being larger than the first threshold value and the second threshold value; before determining that the third assistance is to be implemented, executing an operation (c1) of promoting implementation of the third assistance; in the operation (c1), generating a tension greater than or equal to the third threshold value in the second wire and the fourth wire; when receiving, during execution of the operation (c1), determination that the third assistance is to be implemented, before implementation of the third assistance, executing an operation (c2) indicating that implementation of the third assistance is determined; and in the operation (c2), generating a tension greater than or equal to the fourth threshold value in the second wire and the fourth wire.

The assistance method according to the aspect of the present disclosure may further include, in third assistance for assisting the user in lifting an object, generating a tension greater than a fifth threshold value in the second wire and the fourth wire, the fifth threshold value being larger than the first threshold value and the second threshold value; before determining that the third assistance is to be implemented, executing an operation (c1) of promoting implementation of the third assistance; in the operation (c1), generating a tension greater than or equal to the third threshold value in the second wire and the fourth wire; when receiving, during execution of the operation (c1), determination that the third assistance is to be implemented, before implementation of the third assistance, executing an operation (c2) indicating that implementation of the third assistance is determined; and in the operation (c2), generating a tension greater than or equal to the fourth threshold value in the second wire and the fourth wire.

The assistance method according to the aspect of the present disclosure, a first end of the first wire may be fixed to the left knee belt, a second end of the first wire may be fixed to a first motor among the at least one motor, a first end of the second wire may be fixed to the left knee belt, a second end of the second wire may be fixed to a second motor among the at least one motor, a first end of the third wire may be fixed to the right knee belt, a second end of the third wire may be fixed to a third motor among the at least one motor, a first end of the fourth wire may be fixed to the right knee belt, and a second end of the fourth wire may be fixed to a fourth motor among the at least one motor.

The assistance method according to the aspect of the present disclosure may further include coupling, using a fifth wire among the wires, the upper-body belt and the left knee belt to each other, the fifth wire extending on or above the front part of the body of the user in a direction crossing a direction in which the first wire extends; coupling, using a sixth wire among the wires, the upper-body belt and the left knee belt to each other, the sixth wire extending on or above the back part of the body of the user in a direction crossing a direction in which the second wire extends; coupling, using a seventh wire among the wires, the upper-body belt and the right knee belt to each other, the seventh wire extending on or above the front part of the body of the user in a direction crossing a direction in which the third wire extends; coupling, using an eighth wire among the wires, the upper-body belt and the right knee belt to each other, the eighth wire extending on or above the back part of the body of the user in a direction crossing a direction in which the fourth wire extends; in the first assistance, generating a tension greater than or equal to the first threshold value in the first wire and the fifth wire during the first period; generating a tension greater than or equal to the first threshold value in the second wire and the sixth wire during the second period; generating a tension greater than or equal to the first threshold value in the third wire and the seventh wire during the third period; generating a tension greater than or equal to the first threshold value in the fourth wire and the eighth wire during the fourth period; generating a tension less than the second threshold value in the first wire and the fifth wire during the fifth period; generating a tension greater than or equal to the second threshold value in the second wire and the sixth wire during the sixth period;

generating a tension less than the second threshold value in the third wire and the seventh wire during the seventh period; and generating a tension greater than or equal to the second threshold value in the fourth wire and the eighth wire during the eighth period.

In the assistance method according to the aspect of the present disclosure, a time point of 50% of the gait phase of the left leg may correspond to a time point of 0% of the gait phase of the right leg, and a time point of 50% of the gait phase of the right leg may correspond to a time point of 0% of the gait phase of the left leg.

The assistance method according to the aspect of the present disclosure may further include acquiring a sensor value of a sensor that detects a gait cycle of the user; and calculating the gait phase of the left leg and the gait phase of the right leg based on the sensor value.

The assistance method according to the aspect of the present disclosure may further include, in second assistance for assisting the user in walking while carrying no object, generating a tension less than the second threshold value in the first wire during the fifth period; generating a tension less than the second threshold value in the second wire during the sixth period; generating a tension less than the second threshold value in the third wire during the seventh period; generating a tension less than the second threshold value in the fourth wire during the eighth period, the tension of the second wire in the sixth period during the second assistance being less than the tension of the second wire in the sixth period during the first assistance, the tension of the fourth wire in the eighth period during the second assistance being less than the tension of the fourth wire in the eighth period during the first assistance; before determining that the second assistance is to be implemented, executing operations (b1) and (b2) of promoting implementation of the second assistance; in the operation (b1), generating a tension greater than or equal to the third threshold value in the second wire and the third wire; in the operation (b2), generating a tension greater than or equal to the third threshold value in the first wire and the fourth wire; when receiving, during execution of the operations (b1) and (b2), determination that the second assistance is to be implemented, before implementation of the second assistance, executing operations (b3) and (b4) indicating that implementation of the second assistance is determined; in the operation (b3), generating a tension greater than or equal to the fourth threshold value in the second wire and the third wire; in the operation (b4), generating a tension greater than or equal to the fourth threshold value in the first wire and the fourth wire; accepting selection of an assistance method including at least one of the first assistance, the second assistance, or the third assistance via an interface device; and generating a tension in the first wire, the second wire, the third wire, and the fourth wire in accordance with the accepted assistance method.

A recording medium according to still another aspect of the present disclosure is a recording medium storing a control program for causing a device including a processor to execute a process. The recording medium is a non-volatile, computer-readable medium. A first wire couples an upper-body belt and a left knee belt to each other on or above a front part of a body of a user, the upper-body belt being a belt to be worn on an upper half of the body of the user, the left knee belt being a belt to be worn on a left knee of the user. A second wire couples the upper-body belt and the left knee belt to each other on or above a back part of the body of the user. A third wire couples the upper-body belt and a right knee belt to each other on or above the front part of the

body of the user, the right knee belt being a belt to be worn on a right knee of the user. A fourth wire couples the upper-body belt and the right knee belt to each other on or above the back part of the body of the user. The process 5 includes, when assisting the user in walking while carrying an object, causing at least one motor to generate a tension greater than or equal to a first threshold value in the first wire during a first period, the first period being a period of 35% or more and 90% or less of a gait phase of a left leg of the user; causing the at least one motor to generate a tension greater than or equal to the first threshold value in the second wire during a second period, the second period being a period of 0% or more and 25% or less and 65% or more and less than 100% of the gait phase of the left leg; causing the 10 at least one motor to generate a tension greater than or equal to the first threshold value in the third wire during a third period, the third period being a period of 35% or more and 90% or less of a gait phase of a right leg of the user; causing the at least one motor to generate a tension greater than or 15 equal to the first threshold value in the fourth wire during a fourth period, the fourth period being a period of 0% or more and 25% or less and 65% or more and less than 100% of the gait phase of the right leg; causing the at least one motor to generate a tension less than a second threshold value in the first wire during a fifth period, the fifth period being a period of 0% or more and less than 100% of the gait phase of the left leg, except the first period; causing the at least one motor to generate a tension greater than or equal to the second threshold value in the second wire during a sixth period, the 20 fifth period being a period of 0% or more and less than 100% of the gait phase of the left leg, except the second period; causing the at least one motor to generate a tension less than the second threshold value in the third wire during a seventh period, the seventh period being a period of 0% or 25 more and less than 100% of the gait phase of the right leg, except the third period; causing the at least one motor to generate a tension greater than or equal to the second threshold value in the fourth wire during an eighth period, the eighth period being a period of 0% or more and less than 100% of the gait phase of the right leg, except the fourth period; before determining that the first assistance is to be 30 implemented, causing the at least one motor to execute operations (a1) to (a3) of promoting implementation of the first assistance; in the operation (a1), causing the at least one motor to generate a tension greater than or equal to a third threshold value in the second wire and the fourth wire; in the operation (a2), causing the at least one motor to generate a tension greater than or equal to the third threshold value in the second wire and the third wire; in the operation (a3), 35 causing the at least one motor to generate a tension greater than or equal to the third threshold value in the first wire and the fourth wire; when receiving, during execution of the operations (a1) to (a3), determination that the first assistance is to be implemented, before implementation of the first assistance, causing the at least one motor to execute operations (a4) to (a6) indicating that implementation of the first assistance is determined; in the operation (a4), causing the at least one motor to generate a tension greater than or equal to a fourth threshold value in the second wire and the fourth wire; in the operation (a5), causing the at least one motor to generate a tension greater than or equal to the fourth threshold value in the second wire and the third wire; and in the operation (a6), causing the at least one motor to generate a tension greater than or equal to the fourth threshold value 40 in the first wire and the fourth wire. The first threshold value is larger than the second threshold value, and the fourth threshold value is larger than the third threshold value. The 45 50 55 60 65

recording medium according to the aspect described above can achieve advantages similar to those of the assistance apparatus according to the aspect of the present disclosure.

It should be noted that the general or specific aspects described above may be implemented as a system, an apparatus, a method, an integrated circuit, a computer program, or a computer-readable recording medium such as a recording disc, or any selective combination thereof. Examples of the computer-readable recording medium include a non-volatile recording medium such as a CD-ROM.

Embodiment

The following specifically describes an assistance apparatus and so on according to an embodiment of the present disclosure with reference to the drawings. The following embodiment describes general or specific examples. Numerical values, shapes, constituent elements, arrangement positions and connection forms of the constituent elements, steps, the order of the steps, and so on in the following embodiment are merely examples and are not intended to limit the present disclosure. The constituent elements mentioned in the following embodiment are described as optional constituent elements unless they are specified in independent claims that define the present disclosure in its broadest concept. The following description of the embodiment may include expressions with the term "approximately", such as approximately parallel or approximately perpendicular. For example, the expression "approximately parallel" is used to mean not only the state of being exactly parallel but also the state of being substantially parallel, that is, the state of being parallel with an error of several percent, for example. This also applies to other expressions with "approximately". In addition, the drawings are illustrative and are not to scale. In the drawings, substantially the same constituent elements are given the same numerals and will not be repeatedly described or will be described in brief.

In this embodiment, an assistance apparatus 100 will be described as an assistance apparatus that assists a user wearing the assistance apparatus 100 in walking. Specifically, the assistance apparatus 100 according to the embodiment will be described as an assistance apparatus that actively supports flexion and extension of the hip joints of the user to allow the user to walk. In this embodiment, the term "actively supporting" may refer not only to supporting flexion and extension forces, which are required for the hip joints, during flexion and extension of the hip joints of the user to walk in the direction of travel but also to applying a force for causing flexion and extension of the hip joints and to physically controlling the amount of flexion and extension of the hip joints to the desired amount of flexion and extension, that is, physically controlling movements of the hip joints of the user. As used herein, the term "assisting the user" by the assistance apparatus 100 is used to include both actively supporting the movement of the user and supporting the movement of the user in an auxiliary manner.

1. Configuration of Assistance Apparatus According to Embodiment

The assistance apparatus 100 according to the embodiment will be described with reference to FIG. 1 to FIG. 3. FIG. 1 is a front view of a user 1 wearing the assistance apparatus 100 according to the embodiment, as viewed from the front. FIG. 2 is a back view of the user 1 wearing the assistance apparatus 100 illustrated in FIG. 1. FIG. 3 is a

block diagram illustrating a functional configuration of the assistance apparatus 100 according to the embodiment.

As illustrated in FIG. 1 to FIG. 3, the assistance apparatus 100 includes an upper-body belt 111, a left knee belt 112a, 5 a right knee belt 112b, and wires 110. The assistance apparatus 100 further includes motors 114, force sensors 115, and a control unit 120 that controls the operation of the motors 114. The assistance apparatus 100 may include a power supply 130 for supplying electric power to the motors 114 and so on. The power supply 130 may be, for example, a primary battery, a secondary battery, or the like.

The wires 110 include wires 110a1 to 110a4. Each of the wires 110 is coupled to the upper-body belt 111 and the left knee belt 112a or coupled to the upper-body belt 111 and the 15 right knee belt 112b.

The motors 114 include motors 114a1 to 114a4. The wire 110a1 is coupled to the motor 114a1. The wire 110a2 is coupled to the motor 114a2. The wire 110a3 is coupled to the motor 114a3. The wire 110a4 is coupled to the motor 20 114a4.

The force sensors 115 include force sensors 115a1 to 115a4. The force sensor 115a1 is disposed on the wire 110a1. The force sensor 115a2 is disposed on the wire 110a2. The force sensor 115a3 is disposed on the wire 25 110a3. The force sensor 115a4 is disposed on the wire 110a4.

The upper-body belt 111 is worn on the upper half of the body of the user 1. The upper-body belt 111 has a band shape, for example. The upper-body belt 111 includes, near 30 an end portion thereof, a fixing member. Examples of the fixing member include a hook-and-loop fastener such as a Velcro (registered trademark) tape, a fastener such as a hook or a buckle, and a tape. For example, the upper-body belt 111 is wrapped around the waist of the user 1 and is kept 35 wrapped around the waist of the user 1 by using the fixing member. Thus, the upper-body belt 111 is worn on the waist of the user 1. The fixing position of the fixing member is adjusted to change the inner diameter of the wrapped upper-body belt 111. Since the length of the upper-body belt 40 111 can be adjusted, various users 1 with different waist circumferences can wear the upper-body belt 111. The upper-body belt 111 is made of a non-extensible material, for example. Thus, the upper-body belt 111 is less deformable when pulled by the wires 110. The term "upper half of the body", as used herein, is used to include a portion of the body of the user from the shoulder to the waist. The upper-body belt 111 illustrated in FIG. 1 and FIG. 2 has a configuration of a waist belt to be worn on the waist of the user 1. The upper-body belt 111 may be worn on, for 45 example, the waist of the user 1 and/or the shoulder of the user 1 and/or the chest of the user 1.

The upper-body belt 111 may have a tubular shape. In this case, the tubular-shaped upper-body belt 111 may have a larger circumference than the waist circumference of the 50 user 1. The upper-body belt 111 has an adjustment mechanism for adjusting the length of the upper-body belt 111 so that the upper-body belt 111 fits the waist of the user 1. The adjustment mechanism is, for example, a hook-and-loop fastener and may be configured such that a portion of the 55 hook-and-loop fastener having a hook surface is located on an outer periphery of the tubular shape in such a manner as to branch from the outer periphery and a loop surface of the hook-and-loop fastener is located on an outer peripheral surface of the tubular shape. That is, the upper-body belt 111 60 folds back at the portion of the hook-and-loop fastener, and the inner diameter of the tube formed by the upper-body belt 111 changes in accordance with the amount of fold-back.

The left knee belt 112a is worn on the left leg of the user 1 in the vicinity of the left knee, and the right knee belt 112b is worn on the right leg of the user 1 in the vicinity of the right knee. The left knee belt 112a may be worn on any portion of the left leg in a region extending from below the knee to the thigh. The right knee belt 112b may be worn on any portion of the right leg in a region extending from below the knee to the thigh. That is, the term "knee", as used herein, may be used to include a region extending from below the knee to the thigh.

Each of the knee belts 112a and 112b has a band shape, for example, and includes, near an end portion thereof, a fixing member. The knee belts 112a and 112b are the knee left belt 112a and the right knee belt 112b. Examples of the fixing member include a hook-and-loop fastener such as a Velcro (registered trademark) tape, a fastener such as a hook or a buckle, and a tape. Each of the knee belts 112a and 112b is worn on a corresponding one of the thighs of the user 1 or above a corresponding one of the knees of the user 1. For example, each of the knee belts 112a and 112b is wrapped around the corresponding one of the thighs or the like of the user 1 and is kept wrapped around the corresponding one of the thighs or the like of the user 1 by using the fixing member. Thus, the knee belts 112a and 112b are worn on the thighs or the like of the user 1. The fixing positions of the fixing members are adjusted to change the respective inner diameters of the wrapped knee belts 112a and 112b. Since the lengths of the knee belts 112a and 112b can be adjusted, various users 1 having different leg circumferences can wear the knee belts 112a and 112b. The knee belts 112a and 112b may not necessarily be worn over the knee joints. The human thigh has a feature in that the diameter of the thigh becomes larger gradually from the knee toward the hip. Thus, the knee belts 112a and 112b, which are worn on the thighs, namely, above the knees, slip just a little even under tensile forces of the wires 110 when the knee belts 112a and 112b are tightly fastened. In addition, the knee belts 112a and 112b are made of a non-extensible material, for example. Thus, the knee belts 112a and 112b are less deformable when pulled by the wires 110.

Each of the knee belts 112a and 112b may have a tubular shape. In this case, the tubular-shaped knee belts 112a and 112b may have larger circumferences than the thighs of the user 1. The knee belts 112a and 112b have each an adjustment mechanism for adjusting the length of the corresponding one of the knee belts 112a and 112b so that the knee belts 112a and 112b fit the thighs or the like of the user 1. Each of the adjustment mechanisms is, for example, a hook-and-loop fastener and may be configured such that a portion of the hook-and-loop fastener having a hook surface is located on an outer periphery of the tubular shape in such a manner as to branch from the outer periphery and a loop surface of the hook-and-loop fastener is located on an outer peripheral surface of the tubular shape. That is, the knee belts 112a and 112b each fold back at the portion of the hook-and-loop fastener, and the inner diameter of the tube formed by each of the knee belts 112a and 112b changes in accordance with the amount of fold-back.

The motors 114 are arranged on the upper-body belt 111 in a fixed manner. In this embodiment, the motors 114 include four motors 114a1 to 114a4. For example, the motors 114a1 to 114a4 may be accommodated in hollow containers 111a1 to 111a4 included in the upper-body belt 111, respectively. The containers 111a1 to 111a4 may be integrated with the upper-body belt 111 or may be removably attached to the upper-body belt 111. The containers 111a1 to 111a4 may be disposed in the manner illustrated in

FIG. 1 and FIG. 2. In the example illustrated in FIG. 1 and FIG. 2, the containers 111a1, 111a2, 111a3, and 111a4 are located on the left side of the front part, the left side of the back part, the right side of the front part, and the right side of the back part of the body of the user 1, respectively. The motors 114a1, 114a2, 114a3, and 114a4 are accommodated in the containers 111a1, 111a2, 111a3, and 111a4, respectively. The motor 114a1 changes the length of the wire 110a1 between the upper-body belt 111 and the left knee belt 112a to adjust the tension of the wire 110a1. The motor 114a2 changes the length of the wire 110a2 between the upper-body belt 111 and the left knee belt 112a to adjust the tension of the wire 110a2. The motor 114a3 changes the length of the wire 110a3 between the upper-body belt 111 and the right knee belt 112b to adjust the tension of the wire 110a3. The motor 114a4 changes the length of the wire 110a4 between the upper-body belt 111 and the right knee belt 112b to adjust the tension of the wire 110a4.

In this embodiment, each of the motors 114a1 to 114a4 includes a pulley, a drive shaft for rotating the pulley, and an electric motor for driving the drive shaft to rotate. The pulley of each of the motors 114a1 to 114a4 has a corresponding wire among the wires 110a1 to 110a4 wound therearound. The motors 114a1 to 114a4 and the wires 110a1 to 110a4 have a one-to-one correspondence. The respective pulleys, drive shafts, and electric motors of the motors 114a1 to 114a4 are accommodated in the containers 111a1 to 111a4, respectively. Each of the motors 114a1 to 114a4 may include an electric motor, but may include no pulley or drive shaft. Alternatively, the upper-body belt 111 may include pulleys and drive shafts, each pulley and drive shaft being associated with one of the motors 114a1 to 114a4. In this case, a rotating shaft of the electric motor is coupled to the drive shaft for the pulley in such a manner that a rotational driving force can be transmitted to the drive shaft. Instead of the motors 114a1 to 114a4, for example, a device capable of adjusting the lengths of the wires 110a1 and 110a2 between the upper-body belt 111 and the left knee belt 112a and the lengths of the wires 110a3 and 110a4 between the upper-body belt 111 and the right knee belt 112b, such as a linear actuator or a pneumatic or hydraulic piston, may be used. In the assistance apparatus 100 having the configuration described above, the wound portions of the wires 110a1 to 110a4 and the motors 114a1 to 114a4 are located on the upper-body belt 111, and the wires 110a1 to 110a4 and the knee belts 112a and 112b are located below the upper-body belt 111. Accordingly, the assistance apparatus 100 achieves a simple and compact configuration.

In this embodiment, the wires 110 include four wires 110a1 to 110a4. The motor 114a1 is coupled to the wire 110a1, the motor 114a2 is coupled to the wire 110a2, the motor 114a3 is coupled to the wire 110a3, and the motor 114a4 is coupled to the wire 110a4 so as to individually adjust the lengths of the wires 110a1 to 110a4.

Each of the wires 110a1 and 110a2 has one end fixed to the left knee belt 112a. The wire 110a1 has another end coupled to the motor 114a1, and the wire 110a2 has another end coupled to the motor 114a2. That is, the other end of the wire 110a1 and the other end of the wire 110a2 are fixed. The wire 110a1 couples the left knee belt 112a and the motor 114a1 to each other, and the wire 110a2 couples the left knee belt 112a and the motor 114a2 to each other.

Each of the wires 110a3 and 110a4 has one end fixed to the right knee belt 112b. The wire 110a3 has another end coupled to the motor 114a3, and the wire 110a4 has another end coupled to the motor 114a4. That is, the other end of the wire 110a3 and the other end of the wire 110a4 are fixed.

The wire **110a3** couples the right knee belt **112b** and the motor **114a3** to each other, and the wire **110a4** couples the right knee belt **112b** and the motor **114a4** to each other.

In this embodiment, each of the motors **114a1** to **114a4** rotates the pulley in the forward or reverse direction to wind or unwind the corresponding wire among the wires **110a1** to the **110a4** around the pulley. The wires **110a1** to **110a4** described above are fixed to the waist of the user **1** by the upper-body belt **111** and are fixed to the left and right thighs or the like of the user **1** by the knee belts **112a** and **112b**.

As described above, each of the wires **110a1** to **110a4** couples the upper-body belt **111** to the left knee belt **112a** or the right knee belt **112b**. The wires **110a1** to **110a4** may be coupled to the upper-body belt **111** directly or indirectly. Each of the wires **110a1** to **110a4** may be coupled to the left knee belt **112a** or the right knee belt **112b** directly or indirectly. In the example described above, the one end of each of the wires **110a1** to **110a4** is fixed to, or is directly coupled to, the left knee belt **112a** or the right knee belt **112b**, and the other end of each of the wires **110a1** to **110a4** is fixed to, or is indirectly coupled to, the upper-body belt **111** via the corresponding one of the motors **114**. However, each of the wires **110** may be coupled to the upper-body belt **111** and each of the wires **110** may be coupled to the left knee belt **112a** or the right knee belt **112b** by using the following configuration, for example.

Specifically, the one end of each of the wires **110** may be indirectly coupled to the left knee belt **112a** or the right knee belt **112b** via the corresponding one of the motors **114**, and the other end of each of the wires **110** may be directly coupled to the upper-body belt **111**. Alternatively, both ends of each of the wires **110** may be directly coupled to the upper-body belt **111** and to the left knee belt **112a** or the right knee belt **112b**, and a motor, a linear actuator, or a pneumatic or hydraulic piston may be disposed in the middle of each of the wires **110** to adjust the length of the wire **110**.

Alternatively, the one end of each of the wires **110** may be directly coupled to the left knee belt **112a** or the right knee belt **112b**, and the other end of each of the wires **110** may be indirectly coupled to the left knee belt **112a** or the right knee belt **112b** via the corresponding one of the motors **114** in such a manner that each of the wires **110** is arranged to reciprocate between the left knee belt **112a** or the right knee belt **112b** and the upper-body belt **111**. Alternatively, the one end of each of the wires **110** may be directly coupled to the upper-body belt **111**, and the other end of each of the wires **110** may be indirectly coupled to the upper-body belt **111** via the corresponding one of the motors **114** in such a manner that each of the wires **110** is arranged to reciprocate between the upper-body belt **111** and the left knee belt **112a** or the right knee belt **112b**. The wires **110** may be arranged such that two of the wires **110** are located in the same location, for example, on or above the front part of the left leg with the upper-body belt **111** interposed therebetween and the corresponding motors among the motors **114** are rotated to move the two wires **110** in different directions to thereby assist flexion.

Alternatively, both ends of each of the wires **110** may be coupled to the corresponding one of the motors **114** and may be arranged to form a ring through the motor **114**. In this case, each of the wires **110** is arranged to reciprocate between the upper-body belt **111** and the left knee belt **112a** or the right knee belt **112b**, and each of the motors **114** changes the length of the circumference of the ring of the corresponding one of the wires **110**.

In any of the configurations described above, each of the wires **110** is coupled to the upper-body belt **111** and the left

knee belt **112a** or the right knee belt **112b** so that the tension thereof is supported by the upper-body belt **111** and the left knee belt **112a** or the right knee belt **112b**. Thus, when each of the motors **114a1** to **114a4** pulls the corresponding wire among the wires **110**, tension that causes the upper-body belt **111** and the left knee belt **112a** or the right knee belt **112b** to come into close proximity to each other is generated in the corresponding wire.

The force sensors **115** include four force sensors **115a1** to **115a4**. The force sensor **115a1** detects the tension of the wire **110a1** and outputs the detected tension to the control unit **120**. The force sensor **115a2** detects the tension of the wire **110a2** and outputs the detected tension to the control unit **120**. The force sensor **115a3** detects the tension of the wire **110a3** and outputs the detected tension to the control unit **120**. The force sensor **115a4** detects the tension of the wire **110a4** and outputs the detected tension to the control unit **120**. The force sensor **115a1** is disposed on the wire **110a1** in the left knee belt **112a**. The force sensor **115a2** is disposed on the wire **110a2** in the left knee belt **112a**. The force sensor **115a3** is disposed on the wire **110a3** in the right knee belt **112b**. The force sensor **115a4** is disposed on the wire **110a4** in the right knee belt **112b**. The force sensors **115a1** to **115a4** may be located in the upper-body belt **111**. Each of the force sensors **115a1** to **115a4** may be capable of detecting the tension of the corresponding wire among the wires **110a1** to **110a4**, and may be a strain gauge force sensor or a piezoelectric force sensor, for example. The force sensors **115a1** to **115a4** and the wires **110a1** to **110a4** have a one-to-one correspondence.

Each of the wires **110a1** to **110a4** may be a metallic wire or a non-metallic wire. Examples of the non-metallic wire include a fiber wire and a fiber belt. A fiber wire or fiber belt is made of a material such as polyester fiber, nylon fiber, acrylic fiber, para-aramid fiber, ultrahigh molecular weight polyethylene fiber, poly-p-phenylenebenzobisoxazole (PBO) fiber, polyarylate fiber, or carbon fiber. In this embodiment, four coupling belts **111b1** to **111b4** are arranged along the wires **110a1** to **110a4**, respectively, and each of the coupling belts **111b1** to **111b4** extends from the upper-body belt **111** to the left knee belt **112a** or the right knee belt **112b**. The coupling belts **111b1** to **111b4** and the wires **110a1** to **110a4** have a one-to-one correspondence. As a non-limiting example, the coupling belts **111b1** to **111b4** are each integrated with the upper-body belt **111** and the left knee belt **112a** or the right knee belt **112b** and are made of a material similar to that of the belts **111**, **112a**, and **112b**. For example, the upper-body belt **111**, the knee belts **112a** and **112b**, and the coupling belts **111b1** to **111b4** may form a single suit having an assistance function that is wearable by the user **1**. Each of the coupling belts **111b1** to **111b4** contains and covers the corresponding wire among the wires **110a1** to **110a4**. The coupling belts **111b1** to **111b4** may be collectively referred to as coupling belts **111b**.

The arrangement configuration of the wires **110a1** to **110a4** will be described in detail with reference to FIG. 1, FIG. 2, and FIG. 4. FIG. 4 schematically illustrates the arrangement of the constituent elements of the assistance apparatus **100** illustrated in FIG. 1. The wire **110a1** couples the upper-body belt **111** and the left knee belt **112a** to each other via the motor **114a1** on or above the front part of the body of the user **1**. The wire **110a1** extends upward from the left knee belt **112a** on or above the front part of the body of the user **1**. The wire **110a2** couples the upper-body belt **111** and the left knee belt **112a** to each other via the motor **114a2** on or above the back part of the body of the user **1**. The wire **110a2** extends upward from the left knee belt **112a** on or

above the back part of the body of the user 1. The wire 110a3 couples the upper-body belt 111 and the right knee belt 112b to each other via the motor 114a3 on or above the front part of the body of the user 1. The wire 110a3 extends upward from the right knee belt 112b on or above the front part of the body of the user 1. The wire 110a4 couples the upper-body belt 111 and the right knee belt 112b to each other via the motor 114a4 on or above the back part of the body of the user 1. The wire 110a4 extends upward from the right knee belt 112b on or above the back part of the body of the user 1. In this manner, the wire 110a1 is located on or above the front part of the left leg of the user 1, the wire 110a2 is located on or above the back part of the left leg of the user 1, the wire 110a3 is located on or above the front part of the right leg of the user 1, and the wire 110a4 is located on or above the back part of the right leg of the user 1. The wires 110a1 to 110a4 are pulled individually to apply forces in different directions to the left and right legs.

In the example illustrated in FIG. 1, FIG. 2, and FIG. 4, the wires 110a1 and 110a3 do not cross each other on or above the front part of the body of the user 1. However, the wires 110a1 and 110a3 may cross each other on or above the front part of the body of the user 1. In the example illustrated in FIG. 1, FIG. 2, and FIG. 4, the wires 110a2 and 110a4 do not cross each other on or above the back part of the body of the user 1. However, the wires 110a2 and 110a4 may cross each other on or above the back part of the body of the user 1.

The motors 114a1 to 114a4 pull the wires 110a1 to 110a4 to apply tensions to the wires 110a1 to 110a4, respectively, and the tensions are transmitted to the left and right legs of the user 1 via the upper-body belt 111 and the knee belts 112a and 112b. To effectively transmit the tensions of the wires 110a1 to 110a4 to the left and right legs of the user 1, the upper-body belt 111 and the knee belts 112a and 112b may have rigidity so as not to be deformable and have inflexibility so as not to be extensible. As described above, examples of the material of the upper-body belt 111 and the knee belts 112a and 112b include a non-extensible material. The upper-body belt 111 and the knee belts 112a and 112b described above are worn by the user 1 in such a manner as to tightly fit the body of the user 1, thus efficiently transmitting the driving forces of the motors 114a1 to 114a4 to the legs of the user 1 through the wires 110a1 to 110a4 and effectively assisting movements of the legs of the user 1. The term "assisting", as used herein, is used to include supporting the movement of the user in order to allow the user to perform a predetermined motion and forcing the body of the user to perform the predetermined motion to induce movements of the body.

A further description will be given of a relationship between tensions applied to the wires 110a1 to 110a4 by the assistance apparatus 100 and motions of the user that are assisted with the tensions. For example, FIG. 5A illustrates example motions of the right leg of the user, which are assisted by the assistance apparatus 100. In the example illustrated in FIG. 5A, the assistance apparatus 100 applies an assistance force to the right leg during the swing phase of gait. The assistance apparatus 100 may apply an assistance force to the right leg during the stance phase of gait. The assistance apparatus 100 also enables the left leg of the user to perform motions similar to those of the right leg. As illustrated in FIG. 5A, the assistance apparatus 100 can apply an assistance force for flexion and extension to the hip joint of the right leg of the user. The flexion of the hip joint is a motion of moving the thigh forward, and the extension of the hip joint is a motion of moving the thigh backward.

The assistance apparatus 100 is also capable of assisting the user in lifting an object using an assistance force for extension. For example, FIG. 5B illustrates an example motion of the user to lift an object, which is assisted by the assistance apparatus 100. In this case, the assistance apparatus 100 applies an assistance force to the hip joint of the left leg and the hip joint of the right leg of the user to extend together. Accordingly, the assistance apparatus 100 assists a user who desires to lift an object in extending the flexed knees and hip joints to stand up from a lean-forward posture to an upright posture.

Further, a relationship between motions of the user, which are induced, or assisted, by the assistance apparatus 100, and assistance forces given to the user through the wires 110a1 to 110a4 will be described with reference to FIG. 6A to FIG. 7B. FIG. 6A illustrates a case where the assistance apparatus 100 according to the embodiment assists flexion of the hip joint of the left leg of the user, and FIG. 6B illustrates a case where the assistance apparatus 100 according to the embodiment assists flexion of the hip joint of the right leg of the user. In FIG. 6A, to flex the left leg, the control unit 120 drives the motor 114a1 to increase the tension of the wire 110a1, that is, to generate a tension in the wire 110a1. In FIG. 6B, to flex the right leg, the control unit 120 drives the motor 114a3 to increase the tension of the wire 110a3. The control unit 120 may control the tensions of the wires 110 in accordance with the detection results of the force sensors 115a1 to 115a4 or in accordance with the amount of driving of the motors 114a1 to 114a4. The details of the control unit 120 will be described below.

In this embodiment, as a non-limiting example, a tension is applied to each of the wires 110a1 to 110a4 in a normal state before flexion. The tension may be applied so as to prevent the corresponding one of the wires 110a1 to 110a4 from loosening and may be less than or equal to 10 N or less than or equal to 5 N, for example. To flex the left leg and the right leg, the tensions of the wires 110a1 and 110a3 are each increased to, for example, a value greater than or equal to 40 N and less than or equal to 100 N. An example for the left leg will be described. A tension greater than or equal to 40 N is exerted on the wire 110a1 for a user, who is a healthy adult male in 20s to 40s. At this time, the user is able to clearly recognize that a force in a flexing direction acts on the left leg and promotes flexion of the left leg. When a tension over 80 N is exerted on the wire 110a1, the left leg of the user is raised in the flexing direction. When the tension exerted on the wire 110a1 is less than or equal to 20 N, the user continues the current motion without substantially perceiving the resistance caused by the tension of the wire 110a1. The tension values described above are examples. The tension values may be changed, as desired, in accordance with the age, gender, body size, or physical activity level of the user, the type of motion of the leg, the degree of assistance on the leg, and so on.

FIG. 7A and FIG. 7B illustrate cases where the assistance apparatus 100 according to the embodiment assists extension of the hip joints of the left and right legs of the user, respectively. In FIG. 7A, the control unit 120 increases the tension of the wire 110a2 to extend the left leg. In FIG. 7B, the control unit 120 increases the tension of the wire 110a4 to extend the right leg. The tensions of the wires 110 during extension may be similar to those during flexion. When assisting the user in lifting an object, the assistance apparatus 100 increases the tensions of the wires 110a2 and 110a4 together and simultaneously assists extension of the hip joints of the left and right legs of the user.

In the foregoing description, the control unit 120 increases the tension of one wire to assist one motion of one leg. At this time, the control unit 120 may control the motors corresponding to the other three wires in accordance with the motion of the user so that the tensions of the other three wires are kept in the current states, and adjust the tensions of the other three wires. The control unit 120 may control the motors corresponding to the other three wires so as not to exert tension on the three wires. For example, the control unit 120 may stop the operation of the motors corresponding to the other three wires.

The assistance apparatus 100 described above is capable of assisting the user in walking by applying assistance torques, which are assistance forces in flexing and extending directions, to the user in accordance with torques generated during the stance phase and swing phase of the leg of the user while the user is walking.

Further, the configuration of the control unit 120 of the assistance apparatus 100 will be described with reference to FIG. 3. The control unit 120 controls the overall operation of the assistance apparatus 100. The control unit 120 determines operations to be individually applied to the wires 110a1 to 110a4 and controls assistance for the hip joints of the user 1. The operations to be individually applied to the wires 110a1 to 110a4 are operation patterns of the wires 110a1 to 110a4, including the timings of applying tensions to the wires 110a1 to 110a4, the magnitudes of the tensions, and periods during which the tensions are applied.

The control unit 120 acquires an instruction entered by the user 1 or the like from an input device 140 included in the assistance apparatus 100 or from a terminal device 150 external to the assistance apparatus 100, and controls the assistance apparatus 100 to start and stop assistance in accordance with the acquired instruction. The input device 140 of the assistance apparatus 100 may be a button, a switch, a key, a touch pad, a microphone of an audio recognition device, or any other suitable device. The terminal device 150 may be a terminal device carried by the user 1 wearing the assistance apparatus 100, and examples of the terminal device 150 include a smartphone, a smartwatch, a tablet, and a personal computer. The control unit 120 may communicate with the input device 140 and the terminal device 150 in a wired or wireless way. The wireless communication may be implemented using a wireless local area network (LAN) such as wireless fidelity (Wi-Fi (registered trademark)), or may be short-range wireless communication such as Bluetooth (registered trademark) or ZigBee (registered trademark), or any other type of wireless communication. The wired communication may be any existing wired communication. The control unit 120 may include a wired or wireless communication circuit. The wired or wireless communication circuit included in the assistance apparatus 100 may be used to perform wired communication or wireless communication. The input device 140 and the terminal device 150 are examples of an interface device.

For example, FIG. 8 illustrates an example input section of the input device 140 included in the assistance apparatus 100 according to the embodiment. The input device 140 includes six physical buttons that accept input. The six buttons include an "ON" button 141 for starting the assistance apparatus 100, an "OFF" button 142 for stopping the operation of the assistance apparatus 100, a "mode" button 143 for switching between operation modes of the assistance apparatus 100, a "set" button 144 for determining an operation mode and so on, a "down" button 145 for decreasing a set value of wire tension and so on, and an "up" button 146 for increasing a set value of wire tension and so on. When

the input section of the input device 140 is a touch panel, each button may be implemented as an icon on a screen. The "down" button 145 and the "up" button 146 may be each a dial, a slide button, a lever such as a joystick, or any other suitable device. In this embodiment, the input device 140 is disposed on the upper-body belt 111, as a non-limiting example. Alternatively, the input device 140 may be disposed on the knee belt 112a or 112b or attached to a part of the body of the user 1, which is away from the upper-body belt 111. The terminal device 150, which is external to the assistance apparatus 100, may have a button configuration similar to that of the input device 140 or an icon configuration on a screen. The operation modes will be described in detail below.

In this embodiment, furthermore, as illustrated in FIG. 9, a contact sensor 301 and at least one of a pressure-sensitive sensor 302 and an inertial measurement unit 303 are attached to the body of the user 1. FIG. 9 illustrates the arrangement of sensors and so on to be attached to the body of the user 1. The contact sensor 301, the pressure-sensitive sensor 302, and the inertial measurement unit 303 output detection results to the control unit 120. The contact sensor 301 is attached to each of the hands of the user 1. Specifically, the contact sensor 301 is attached to a finger tip or the like of gloves worn by the user 1. The contact sensor 301 may be attached to each of both hands of the user 1 or to either hand of the user 1. The contact sensor 301 detects a direct contact and an indirect contact between the hand of the user 1 and an object. Examples of the contact sensor 301 include a contact detection sensor, a touch sensor, a proximity sensor, and a sensor similar to the pressure-sensitive sensor 302. The contact sensor 301 may be attached to each of the arm, chest, abdomen, and so on of the user 1, which may come into contact with an object when the user 1 holds the object.

The pressure-sensitive sensor 302 is attached to each of the soles of the feet of the user 1. Specifically, the pressure-sensitive sensor 302 is attached to each of the bottoms or the like of shoes worn by the user 1. The pressure-sensitive sensor 302 may be attached to each of both feet of the user 1 or to either foot of the user 1. The pressure-sensitive sensor 302 detects a pressure acting on each of the soles of the feet of the user 1, that is, a load. Examples of the pressure-sensitive sensor 302 include a capacitive pressure sensor, a piezoelectric pressure sensor, and a strain gauge pressure sensor. The inertial measurement unit 303 is attached to a portion of the body of the user 1 that moves along with the movement of the user 1, such as the waist in the upper half of the body of the user 1. Specifically, the inertial measurement unit 303 is attached to the upper-body belt 111. The inertial measurement unit 303 includes an acceleration sensor and a gyro sensor (also referred to as an "angular velocity sensor"). The inertial measurement unit 303 may include an acceleration sensor, but may include no gyro sensor. The inertial measurement unit 303 may further include a geomagnetic sensor. The inertial measurement unit 303 detects, on the basis of a detected acceleration and angular velocity, the acceleration of the user 1 in each direction, and the movement direction, movement speed, and movement distance of the user 1. The pressure-sensitive sensor 302 and the inertial measurement unit 303 are examples of a sensor that detects a gait cycle of the user 1.

The contact sensor 301, the pressure-sensitive sensor 302, and the inertial measurement unit 303 exchange information with the control unit 120 via wired communication or wireless communication. The wired communication or wire-

less communication may be any of the wired communication and wireless communication described above.

As illustrated in FIG. 3, the control unit 120 includes a grasp recognition unit 121, a drive control unit 122, a gait timing detection unit 123, a wire tension recognition unit 124, and a storage unit 125. The grasp recognition unit 121, the drive control unit 122, the gait timing detection unit 123, and the wire tension recognition unit 124, which are constituent elements of the control unit 120, may be implemented by a computer system including a processor such as a central processing unit (CPU) or a digital signal processor (DSP) and a memory such as a random access memory (RAM) and a read-only memory (ROM). Some or all of the functions of the constituent elements described above may be achieved by the CPU or the DSP executing a program recorded on the ROM by using the RAM as a work memory. Alternatively, some or all of the functions of the constituent elements described above may be achieved by a dedicated hardware circuit such as an electronic circuit or an integrated circuit. The functions of some or all of the constituent elements described above may be implemented by a combination of the software functions described above and a hardware circuit. The program may be provided as an application by communication via a communication network such as the Internet, communication conforming to a mobile communication standard, communication via any other wireless or wired network, broadcasting, or the like. A computer system and/or a hardware circuit constituted by the control unit 120 may be mounted on the upper-body belt 111, accommodated in the containers 111a1 to 111a4 together with the motors 114a1 to 114a4, or embedded in the upper-body belt 111 at a different location from the motors 114a1 to 114a4, for example. The control unit 120 is an example of a control circuit.

The storage unit 125 is capable of storing information, and the stored information is retrievable from the storage unit 125. The storage unit 125 stores computer programs in accordance with which the constituent elements of the control unit 120 execute processes, threshold values described below, input profiles of wire tensions described below, and so on. The storage unit 125 is implemented as a storage device, for example, a semiconductor memory such as a ROM, a RAM, or a flash memory, a hard disk drive, or a solid state drive (SSD). In this embodiment, the storage unit 125 is included in the control unit 120. Alternatively, the storage unit 125 may be disposed separately from the control unit 120. The storage unit 125 is an example of a memory.

The grasp recognition unit 121 detects a grasp of an object by the user 1 with their hands. The grasp recognition unit 121 determines whether the user 1 is holding an object with their hands on the basis of a change in sensor value, which is acquired from the contact sensor 301. For example, as illustrated in FIG. 10A and FIG. 10B, the contact sensor 301 is a piezoelectric sensor. In this case, the grasp recognition unit 121 detects a time point at which a voltage value corresponding to a sensor value detected by the contact sensor 301 becomes less than a predetermined value, as a time point at which the hands of the user 1 touch an object, that is, as a time point at which the user 1 grasps the object. For example, in the example illustrated in FIG. 10B, the predetermined value is represented by "VA". FIG. 10A illustrates a relationship between contact sensors 301 and the hands of the user. FIG. 10B illustrates an example of a signal of a contact sensor 301. The grasp recognition unit 121 outputs a detection result to the drive control unit 122.

The gait timing detection unit 123 detects a gait timing to determine a timing of assisting the user 1. The gait timing

may include a timing of starting assisting the user 1 during walking, and a timing of determining phases such as a stance phase and a swing phase in a period during which the user 1 takes one step. The drive control unit 122 determines a timing of assisting the user 1 from the gait timing detected by the gait timing detection unit 123 and controls the operation of the motors 114.

Specifically, the gait timing detection unit 123 estimates a gait cycle of the user 1 wearing the assistance apparatus 100, predicts gait phases in the next one step on the basis of the estimation result, and outputs assistance timings based on the predicted gait phases to the drive control unit 122. A gait cycle is a time interval from heel strike of one leg to the next heel strike of the same leg. The gait cycle is constituted by a period of a stance phase and a period of a swing phase. The gait cycle may be sequence of motions occurring from heel strike of one leg to the next heel strike of the same leg.

The gait timing detection unit 123 detects a timing of heel strike of the user 1 on the basis of a sensor value acquired from the pressure-sensitive sensor 302 or on the basis of sensor values acquired from the acceleration sensor and the gyro sensor of the inertial measurement unit 303, and estimates a gait phase for each step, or a gait cycle, of the user 1 in real time. The gait cycles and the steps may be in a one-to-one relationship. Each step of the user 1 is a step with either of the left and right legs. For example, each step of the user 1 corresponds to a period from when the left leg touches the ground to when the left leg touches the ground again. The gait timing detection unit 123 predicts, based on the estimated gait cycle, a gait phase for the next step and a starting time and duration of each of the stance phase and swing phase for the next step, and outputs the prediction results to the drive control unit 122. When the terminal device 150 carried by the user 1 includes an inertial measurement unit, the gait timing detection unit 123 may acquire a sensor value of an acceleration sensor and a sensor value of a gyro sensor from the terminal device 150.

Gait phases represent temporal timings of gait states during a single step taken by the user 1. A time point at which one leg of the user 1 touches the ground corresponds to a time point at which a gait phase is 0%, and a time point at which the same leg of the user 1 touches the ground again corresponds to a time point at which a gait phase is 100%. In a gait phase, timings of gait states of the user 1 are represented in the range of 0% to 100%. For example, a value of 0% to 100% of a gait phase may correspond to the time elapsed from when one leg of the user 1 touches the ground to when the same leg of the user 1 touches the ground again. Specifically, when the time period from when one leg of the user 1 touches the ground to when the same leg of the user 1 touches the ground again is 1 second, the gait phase at the point in time at which a period of 0.5 seconds elapses from the time when the leg of the user 1 touches the ground is represented by 50%.

More specifically, the gait timing detection unit 123 determines a time point at which the leg of the user 1 touches the ground on the basis of the sensor value of the pressure-sensitive sensor 302 in such a manner that, for example, as illustrated in FIG. 11, a time point at which the voltage value corresponding to the pressure sensor value of the pressure-sensitive sensor 302 becomes less than a predetermined value is detected as a timing of heel strike. FIG. 11 illustrates an example of a signal based on signals of the pressure-sensitive sensors 302. For example, the predetermined value is represented by "VB" in FIG. 11. A period during which the pressure-sensitive sensor 302 measures a pressure value greater than or equal to a predetermined value corresponds

to a period of heel contact. The pressure-sensitive sensor 302 is placed at each of the feet of the user 1. The gait timing detection unit 123 acquires a timing at which the shoe touches the ground using the pressure-sensitive sensors 302, rather than a timing that is based on the inertial measurement unit 303 located in the upper-body belt 111 or the like. Thus, the gait timing detection unit 123 can more reliably estimate a gait cycle.

When the inertial measurement unit 303 is used, the gait timing detection unit 123 determines a time point at which the foot of the user 1 touches the ground on the basis of information obtained by the acceleration sensor. For a method for estimating a time point at which a foot touches the ground by using an acceleration sensor, see, for example, IEEE TRANSACTIONS ON BIOMEDICAL ENGINEERING, VOL. 52, NO. 3, 2005, p. 488, FIG. 1, p. 489, FIG. 2. When estimating a gait cycle on the basis of a sensor value of the inertial measurement unit 303, the gait timing detection unit 123 may estimate a gait cycle by using signal waveforms obtained from the acceleration sensor and the gyro sensor. For example, a gait cycle can be estimated by using a signal waveform obtained from the acceleration sensor, as illustrated in FIG. 12. In the example illustrated in FIG. 12, the signal waveform obtained from the acceleration sensor can be used to estimate a time point at which the foot of the user 1 touches the ground, and a gait cycle can be estimated accordingly. FIG. 12 illustrates an example of a signal of the acceleration sensor of the inertial measurement unit 303.

The user 1 may wear an angle sensor (also referred to as a “tilt sensor”). In this case, the angle sensor is attached to, for example, a thigh of the user 1. The gait timing detection unit 123 acquires the angle of the hip joint of the user 1 as gait information. The gait timing detection unit 123 calculates a gait phase on the basis of a cycle of change in the angle of the hip joint of the user 1.

Regardless of which of the pressure-sensitive sensor 302 and the inertial measurement unit 303 is used, for example, the gait timing detection unit 123 may estimate, based on a sensor value of the pressure-sensitive sensor 302 or a sensor value of the inertial measurement unit 303 for the latest three steps of the user 1, an elapsed time of 0% to 100% of a gait phase for each step and may calculate an average value of the three elapsed times. Then, the gait timing detection unit 123 may predict the point in time corresponding to 100% of the gait phase for the next step on the basis of the average value of the elapsed times. Further, the gait timing detection unit 123 may estimate the start timings of the stance phase and the swing phase during the gait phase for each step on the basis of the signal waveform of the sensor and calculate an average value of the start timings for the three steps. Then, the gait timing detection unit 123 may predict, based on the average value, the start timings of the stance phase and the swing phase for the next one step.

Alternatively, the gait timing detection unit 123 may estimate, based on a sensor value of the pressure-sensitive sensor 302 or a sensor value of the inertial measurement unit 303 for the last one step of the user 1, an elapsed time of 0% to 100% of the gait phase for the one step and may predict the point in time corresponding to 100% of the gait phase for the next step on the basis of the estimated elapsed time. Further, the gait timing detection unit 123 may estimate the start timings of the stance phase and the swing phase during the one step on the basis of the sensor values for the last one step of the user 1, and may predict the start timings of the stance phase and the swing phase for the next one step.

The wire tension recognition unit 124 detects the tensions generated in the wires 110a1 to 110a4. The wire tension recognition unit 124 detects the tensions of the wires 110a1 to 110a4 on the basis of sensor values acquired from the force sensors 115a1 to 115a4. The wire tension recognition unit 124 outputs the detected tensions of the wires 110a1 to 110a4 to the drive control unit 122.

The drive control unit 122 controls the motors 114a1 to 114a4, which respectively adjust the tensions of the wires 110a1 to 110a4, on the basis of information on a predicted gait phase of the user 1, which is acquired from the gait timing detection unit 123, and on the basis of information indicating whether the user 1 is carrying an object, which is acquired from the grasp recognition unit 121. The drive control unit 122 starts the motors 114a1 to 114a4, stops the operation of the motors 114a1 to 114a4, and controls the amount by which the wires 110a1 to 110a4 are respectively pulled by the motors 114a1 to 114a4 and the pulling tensions of the wires 110a1 to 110a4. The drive control unit 122 controls the amount of rotation of each of the motors 114a1 to 114a4 and adjusts the rotation torque of each of the motors 114a1 to 114a4, thereby enabling control of the amount by which the corresponding wire among the wires 110 is pulled and the pulling tensions of the corresponding wire.

Specifically, the drive control unit 122 determines a type of assistance to be provided to the user 1 on the basis of the prediction result of the gait timing acquired from the gait timing detection unit 123. Examples of the type of assistance include motions of the leg on which assistance is to be provided to the user 1, such as flexion and extension. In accordance with the type of assistance, the drive control unit 122 further determines a wire to be pulled to assist a motion of the user 1 among the wires 110a1 to 110a4, a tension to be applied to the wire, and a timing of pulling the wire.

Further, the drive control unit 122 changes the relationship between the tension of a wire and the timing of pulling the wire even for the same type of assistance on the basis of information acquired from the grasp recognition unit 121 indicating whether the user 1 is carrying an object.

An assistance correspondence, which is a relationship between the gait timing acquired from the gait timing detection unit 123 and the type of assistance, is set in advance and is stored in, for example, the storage unit 125. A wire-tension relationship, which is a relationship between a wire to be pulled, a tension of the wire, and a timing of pulling the wire, is set in advance in accordance with the type of assistance and information indicating whether the user 1 is carrying an object, and is stored in, for example, the storage unit 125. The wire-tension relationship may be updated on the basis of the achievement of assistance-based control by the assistance apparatus 100. On the basis of information on the assistance correspondence and the wire-tension relationship, which are stored in the storage unit 125, the drive control unit 122 determines a type of assistance to be provided to the user 1 and determines control of wires corresponding to the determined type of assistance. The drive control unit 122 controls the motors linked to the determined wires, in accordance with tensions to be applied to the wires and timings of pulling the wires.

Further, the drive control unit 122 controls the operation of the motors 114a1 to 114a4 on the basis of information on the tensions of the wires 110a1 to 110a4, which is acquired from the wire tension recognition unit 124, so that the tensions of the wires 110a1 to 110a4 have predetermined levels. In addition, the drive control unit 122 may change the wire-tension relationship on the basis of, in addition to the

information acquired from the grasp recognition unit 121, the gait timing detection unit 123, and the wire tension recognition unit 124, information on the user 1, such as age, gender, body size, and physical activity level, the degree of assistance on the leg, and so on, and may use the changed wire-tension relationship.

2. Modification of Assistance Apparatus

In the assistance apparatus 100 described above, the upper-body belt 111 is coupled to the knee belts 112a and 112b by using the four wires 110a1 to 110a4. However, the number of wires is not limited to that in the embodiment. For example, as illustrated in FIG. 13 to FIG. 17, eight wires may be used. FIG. 13 is a perspective view of a user 1 wearing an assistance apparatus 200 according to a modification of the embodiment, as viewed obliquely from the front. FIG. 14 is a front view of the user 1 wearing the assistance apparatus 200 illustrated in FIG. 13. FIG. 15 is a back view of the user 1 wearing the assistance apparatus 200 illustrated in FIG. 13. FIG. 16 is a diagram schematically illustrating the arrangement of constituent elements of the assistance apparatus 200 illustrated in FIG. 13. FIG. 17 is a block diagram illustrating a functional configuration of the assistance apparatus 200 illustrated in FIG. 13.

As illustrated in FIG. 13 to FIG. 17, the assistance apparatus 200 according to the modification includes an upper-body belt 111, knee belts 112a and 112b, and eight wires, namely, first to eighth wires 110a1 to 110a8. The assistance apparatus 200 further includes a motor 114a1 linked to the first wire 110a1, a motor 114a2 linked to the second wire 110a2, a motor 114a3 linked to the third wire 110a3, a motor 114a4 linked to the fourth wire 110a4, a motor 114a5 linked to the fifth wire 110a5, a motor 114a6 linked to the sixth wire 110a6, a motor 114a7 linked to the seventh wire 110a7, a motor 114a8 linked to the eighth wire 110a8, a force sensor 115a1 disposed on the first wire 110a1, a force sensor 115a2 disposed on the second wire 110a2, a force sensor 115a3 disposed on the third wire 110a3, a force sensor 115a4 disposed on the fourth wire 110a4, a force sensor 115a5 disposed on the fifth wire 110a5, a force sensor 115a6 disposed on the sixth wire 110a6, a force sensor 115a7 disposed on the seventh wire 110a7, a force sensor 115a8 disposed on the eighth wire 110a8, and a control unit 120.

The upper-body belt 111 includes containers 111a1, 111a2, 111a3, and 111a4 so as to correspond to the front part, left side part, back part, and right side part of the body of the user 1, respectively. The motors 114a1 and 114a3 are accommodated in the container 111a1, the motors 114a5 and 114a6 are accommodated in the container 111a2, the motors 114a2 and 114a4 are accommodated in the container 111a3, and the motors 114a7 and 114a8 are accommodated in the container 111a4.

The first wire 110a1 and the fifth wire 110a5 are arranged to extend in directions crossing each other on or above the front part of the body of the user 1, and, more specifically, are arranged to cross each other. Each of the first wire 110a1 and the fifth wire 110a5 has one end fixed to the left knee belt 112a. The first wire 110a1 has another end coupled to the motor 114a1, and the fifth wire 110a5 has another end coupled to the motor 114a5. That is, the first wire 110a1 couples the left knee belt 112a and the motor 114a1 to each other, and the fifth wire 110a5 couples the left knee belt 112a and the motor 114a5 to each other.

The second wire 110a2 and the sixth wire 110a6 are arranged to extend in directions crossing each other on or above the back part of the body of the user 1, and, more specifically, are arranged to cross each other. Each of the

second wire 110a2 and the sixth wire 110a6 has one end fixed to the left knee belt 112a. The second wire 110a2 has another end coupled to the motor 114a2, and the sixth wire 110a6 has another end coupled to the motor 114a6. That is, the second wire 110a2 couples the left knee belt 112a and the motor 114a2 to each other, and the sixth wire 110a6 couples the left knee belt 112a and the motor 114a6 to each other.

The third wire 110a3 and the seventh wire 110a7 are arranged to extend in directions crossing each other on or above the front part of the body of the user 1, and, more specifically, are arranged to cross each other. Each of the third wire 110a3 and the seventh wire 110a7 has one end fixed to the right knee belt 112b. The third wire 110a3 has another end coupled to the motor 114a3, and the seventh wire 110a7 has another end coupled to the motor 114a7. That is, the third wire 110a3 couples the right knee belt 112b and the motor 114a3 to each other, and the seventh wire 110a7 couples the right knee belt 112b and the motor 114a7 to each other.

The fourth wire 110a4 and the eighth wire 110a8 are arranged to extend in directions crossing each other on or above the back part of the body of the user 1, and, more specifically, are arranged to cross each other. Each of the fourth wire 110a4 and the eighth wire 110a8 has one end fixed to the right knee belt 112b. The fourth wire 110a4 has another end coupled to the motor 114a4, and the eighth wire 110a8 has another end coupled to the motor 114a8. That is, the fourth wire 110a4 couples the right knee belt 112b and the motor 114a4 to each other, and the eighth wire 110a8 couples the right knee belt 112b and the motor 114a8 to each other.

Further, the first wire 110a1 and the second wire 110a2 extend upward and toward the right side of the body of the user 1 from the left knee belt 112a. Specifically, the first wire 110a1 and the second wire 110a2 extend to the right side of the body of the user 1 while extending upward from the left knee belt 112a, and, for example, extend upward and diagonally to the right from the left knee belt 112a. The fifth wire 110a5 and the sixth wire 110a6 extend upward and toward the left side of the body of the user 1 from the left knee belt 112a. Specifically, the fifth wire 110a5 and the sixth wire 110a6 extend to the left side of the body of the user 1 while extending upward from the left knee belt 112a, and, for example, extend upward and diagonally to the left from the left knee belt 112a. The third wire 110a3 and the fourth wire 110a4 extend upward and toward the left side of the body of the user 1 from the right knee belt 112b. Specifically, the third wire 110a3 and the fourth wire 110a4 extend to the left side of the body of the user 1 while extending upward from the right knee belt 112b, and, for example, extend upward and diagonally to the left from the right knee belt 112b. The seventh wire 110a7 and the eighth wire 110a8 extend upward and toward the right side of the body of the user 1 from the right knee belt 112b. Specifically, the seventh wire 110a7 and the eighth wire 110a8 extend to the right side of the body of the user 1 while extending upward from the right knee belt 112b, and, for example, extend upward and diagonally to the right from the right knee belt 112b.

Extending of two wires in directions crossing each other is equivalent to crossing of directions in which the two wires extend. Further, crossing of directions in which the two wires extend is equivalent to extending of the two wires in directions that are not parallel to each other. The directions may cross each other at an intersection, or may have no intersection therebetween and may not cross each other. Thus, the two wires may actually cross each other at an

intersection or may not actually cross each other. Such two wires extending in directions crossing each other may or may not cross each other when the user 1 is viewed from outside the user 1. When the two wires do not cross each other, as illustrated in FIG. 18 and FIG. 19, the two wires may extend to form a V shape, for example, or may extend away from each other. FIG. 18 and FIG. 19 illustrate modifications of the arrangement of the wires 110 in the assistance apparatus 200 illustrated in FIG. 13.

In this modification, furthermore, eight coupling belts 111b1 to 111b8 are arranged along the first wire 110a1 to the eighth wire 110a8, respectively, and each of the eight coupling belts 111b1 to 111b8 extends from the upper-body belt 111 to the left knee belt 112a or the right knee belt 112b. The coupling belts 111b1 to 111b8 and the first wire 110a1 to the eighth wire 110a8 have a one-to-one correspondence.

In this modification, as a non-limiting example of pairs of two wires extending in directions crossing each other, two wires in each pair of wires cross each other to form an X shape. The first wire 110a1 to the eighth wire 110a8 may have any other arrangement configuration. As illustrated in FIG. 18, for example, the first wire 110a1 and the fifth wire 110a5 may be arranged to form a V shape. In this case, the first wire 110a1 and the fifth wire 110a5 may form a tapered shape that becomes wider toward the top from the left knee belt 112a. In addition, on the left knee belt 112a, the first wire 110a1 and the fifth wire 110a5 may be arranged in close proximity to each other in the manner illustrated in FIG. 18 or may be arranged away from each other in the manner illustrated in FIG. 19. The same applies to the other pairs of wires.

Alternatively, as illustrated in FIG. 20, for example, the first wire 110a1 and the fifth wire 110a5 may be arranged to form an inverted V shape. In this case, the first wire 110a1 and the fifth wire 110a5 may form a tapered shape that becomes narrower toward the top from the left knee belt 112a. In addition, on the upper-body belt 111, the first wire 110a1 and the fifth wire 110a5 may be arranged in close proximity to each other in the manner illustrated in FIG. 20 or may be arranged away from each other in the manner illustrated in FIG. 21. The same applies to the other pairs of wires 110. FIG. 20 and FIG. 21 illustrate modifications of the arrangement of the wires 110 in the assistance apparatus 200 illustrated in FIG. 13.

In FIG. 13 to FIG. 15, the first wire 110a1 and the third wire 110a3 extending from the container 111a1 form an inverted V shape, the fifth wire 110a5 and the sixth wire 110a6 extending from the container 111a2 form an inverted V shape, the second wire 110a2 and the fourth wire 110a4 extending from the container 111a3 form an inverted V shape, and the seventh wire 110a7 and the eighth wire 110a8 extending from the container 111a4 form an inverted V shape. However, the arrangement of the first wire 110a1 to the eighth wire 110a8 on the upper-body belt 111 is not limited to the arrangement described above. For example, a wound portion of the first wire 110a1 and a wound portion of the third wire 110a3 may be arranged away from each other so that the two wires 110a1 and 110a3 do not cross each other or may be arranged so that the two wires 110a1 and 110a3 cross each other to form an X shape. A wound portion of the fifth wire 110a5 and a wound portion of the sixth wire 110a6 may be arranged away from each other so that the two wires 110a5 and 110a6 do not cross each other or may be arranged so that the two wires 110a5 and 110a6 cross each other to form an X shape. A wound portion of the second wire 110a2 and a wound portion of the fourth wire 110a4 may be arranged away from each other so that the two

wires 110a2 and 110a4 do not cross each other or may be arranged so that the two wires 110a2 and 110a4 cross each other to form an X shape. A wound portion of the seventh wire 110a7 and a wound portion of the eighth wire 110a8 may be arranged away from each other so that the two wires 110a7 and 110a8 do not cross each other or may be arranged so that the two wires 110a7 and 110a8 cross each other to form an X shape.

In the assistance apparatus 200 described above, for example, the motor 114a1 generates a tension in the first wire 110a1, and the motor 114a5 generates a tension in the fifth wire 110a5. The assistance apparatus 200 drives the motor 114a1 to increase the tension of the first wire 110a1. Thus, a force is exerted on the leg of the user 1 in a direction in which the distance between the knee and the heel is reduced to assist a motion of the ankle of the user 1 during walking. The assistance apparatus 200 drives the motor 114a5 to increase the tension of the fifth wire 110a5. Thus, a force is exerted on the leg of the user 1 in a direction in which the distance between the knee and the heel is reduced to assist a motion of the ankle of the user 1 during walking. Further, by setting the tensions of the first wire 110a1 and the fifth wire 110a5 to different values, the assistance apparatus 200 can generate a moment of force regarding a left or right tilt of the heel of the user 1 and can assist a motion of the ankle of the user 1 during walking.

The assistance apparatus 200 can apply an assistance force to the hip joint of the left leg and the hip joint of the right leg of the user 1 to flex and extend the hip joints. Referring to FIG. 22A, a case is illustrated in which the assistance apparatus 200 according to the modification assists flexion of the hip joint of the left leg of the user 1. Referring to FIG. 22B, a case is illustrated in which the assistance apparatus 200 according to the modification assists flexion of the hip joint of the right leg of the user 1. In FIG. 22A, to flex the left leg, the drive control unit 122 drives the motors 114a1 and 114a5 to increase the tensions of the first wire 110a1 and the fifth wire 110a5. In FIG. 22B, to flex the right leg, the drive control unit 122 drives the motors 114a3 and 114a7 to increase the tensions of the third wire 110a3 and the seventh wire 110a7. In this modification, the tensions of the first wire 110a1 and the fifth wire 110a5 are assumed to be equivalent, but may be different. In this modification, the tensions of the third wire 110a3 and the seventh wire 110a7 are assumed to be equivalent, but may be different.

Referring to FIG. 23A, a case is illustrated in which the assistance apparatus 200 according to the modification assists extension of the hip joint of the left leg of the user 1. Referring to FIG. 23B, a case is illustrated in which the assistance apparatus 200 according to the modification assists extension of the hip joint of the right leg of the user 1. In FIG. 23A, to extend the left leg, the drive control unit 122 increases the tensions of the second wire 110a2 and the sixth wire 110a6. In FIG. 23B, to extend the right leg, the drive control unit 122 increases the tensions of the fourth wire 110a4 and the eighth wire 110a8. The tension of the second wire 110a2 for extension may be similar to the tension of the first wire 110a1 for flexion. The tension of the sixth wire 110a6 for extension may be similar to the tension of the fifth wire 110a5 for flexion. The tension of the fourth wire 110a4 for extension may be similar to the tension of the third wire 110a3 for flexion. The tension of the eighth wire 110a8 for extension may be similar to the tension of the seventh wire 110a7 for flexion.

In the foregoing description, the drive control unit 122 increases the tensions of two wires among the wires 110 to

assist one motion of one leg. In this case, the drive control unit 122 may control the motors 114 to adjust the tensions of the wires 110 in accordance with a motion of the user 1 while keeping the tensions of the other six wires at the current value, or may stop the motors 114 corresponding to the six wires so as not to exert the tensions on the six wires.

3. Operation of Assistance Apparatus

3.1. Overall Operation of Assistance Apparatus

Next, the overall operation flow of an assistance apparatus will be described. Since the assistance apparatus 100 according to the embodiment and the assistance apparatus 200 according to the modification are similar in terms of the overall operation flow of an assistance apparatus, the operation of the assistance apparatus 100 according to the embodiment will be described, with no description given of the operation of the assistance apparatus 200 according to the modification. FIG. 24 is a flowchart illustrating the overall flow of an operation of the assistance apparatus 100 for assisting the user 1.

As illustrated in FIG. 3 and FIG. 24, in step S001, the control unit 120 of the assistance apparatus 100 acquires, or receives, an instruction for an operation mode from the user 1. The control unit 120 determines the operation mode of the assistance apparatus 100 in accordance with the acquired instruction. Specifically, the drive control unit 122 receives an instruction for an operation mode to be implemented by the assistance apparatus 100 from the input device 140 of the assistance apparatus 100 or from the terminal device 150 or the like. Examples of the operation mode include a normal walking mode, an object transport walking mode, a lifting mode, and a calibration mode. The normal walking mode is a mode for assisting a user in walking while carrying no object such as an item like luggage. The object transport walking mode is a mode for assisting a user in walking while carrying an object. The lifting mode is a mode for assisting a user in lifting an object. The calibration mode is a mode for setting a maximum tension to be generated in each wire. In the calibration mode, a maximum tension to be generated in each wire can be set for each user.

In step S002, the drive control unit 122 of the control unit 120 determines whether the instruction indicates the normal walking mode. If the instruction indicates the normal walking mode (Yes in step S002), the drive control unit 122 proceeds to step S003. If the instruction does not indicate the normal walking mode (No in step S002), the drive control unit 122 proceeds to step S006.

In step S003, the drive control unit 122 acquires a gait phase predicted by the gait timing detection unit 123. Then, in step S004, the drive control unit 122 controls the motors 114a1 to 114a4 on the basis of the acquired gait phase to generate tensions in the wires 110a1 to 110a4 of the assistance apparatus 100 in accordance with the input profiles corresponding to the normal walking mode. The input profiles of wire tensions for the normal walking mode are input profiles corresponding to "walking with no object", namely, no object carried by the user 1. The drive control unit 122 generates tensions in the wires 110a1 to 110a4 to assist the user 1 in flexing and extending the left and right legs. In this case, the drive control unit 122 controls the tension of the wire 110a1 on the basis of the tension of the wire 110a1, which is acquired from the force sensor 115a1, controls the tension of the wire 110a2 on the basis of the tension of the wire 110a2, which is acquired from the force sensor 115a2, controls the tension of the wire 110a3 on the basis of the tension of the wire 110a3, which is acquired from the force sensor 115a3, and controls the tension of the wire 110a4 on the basis of the tension of the wire 110a4,

which is acquired from the force sensor 115a4. In this way, the assistance apparatus 100 assists the user 1 in walking while carrying no object. That is, the assistance apparatus 100 provides walking-with-no-object assistance. The input profiles corresponding to the walking-with-no-object assistance will be described in detail below.

Each input profile includes a timing at which a tension is generated in a wire during a gait cycle of the left leg, a period during which a tension is generated in the wire, the value of the tension of the wire during the period, a timing at which a tension is generated in a wire during a gait cycle of the right leg, a period during which a tension is generated in the wire, and the value of the tension of the wire during the period. The input profiles are set in advance and are stored in the storage unit 125. While receiving assistance provided by the assistance apparatus 100, the user 1 may adjust the timing of generation of a wire tension, the period of generation of the wire tension, and the value of the wire tension via the input device 140 or the terminal device 150. The drive control unit 122 may reflect the adjustment results to change the input profile, and may store the changed input profile in the storage unit 125. The drive control unit 122 may control the wire tension by using the changed input profile.

Then, in step S005, the drive control unit 122 determines whether a stop instruction for stopping assistance provided by the assistance apparatus 100 has been acquired from the user 1. If the stop instruction has been acquired (Yes in step S005), the drive control unit 122 stops the operation of the assistance apparatus 100 and terminates the series of processes. If no stop instruction is acquired (No in step S005), the drive control unit 122 returns to step S003. The stop instruction may be an instruction for changing the operation mode.

In step S006, the drive control unit 122 determines whether the instruction indicates the object transport walking mode. If the instruction indicates the object transport walking mode (Yes in step S006), the drive control unit 122 proceeds to step S007. If the instruction does not indicate the object transport walking mode (No in step S006), the drive control unit 122 proceeds to step S013.

In step S007, the grasp recognition unit 121 determines whether the user 1 is carrying an object. The grasp recognition unit 121 detects whether the user 1 is carrying an object on the basis of a sensor value acquired from the contact sensor 301 that the user 1 wears on their hand, and outputs a detection result to the drive control unit 122. If the grasp recognition unit 121 determines that the user 1 is carrying an object (Yes in step S007), the process proceeds to step S008. If the grasp recognition unit 121 determines that the user 1 is carrying no object (No in step S007), the process proceeds to step S010.

In step S008, the drive control unit 122 acquires a gait phase predicted by the gait timing detection unit 123. Then, in step S009, the drive control unit 122 controls the motors 114 on the basis of the acquired gait phase to generate tensions in the wires 110 of the assistance apparatus 100 in accordance with input profiles corresponding to "walking with object", namely, an object carried by the user 1. The drive control unit 122 controls the tensions of the wires 110, each of which is acquired from the corresponding one of the force sensors 115, to assist the user 1 in flexing and extending each of the left and right legs. In this way, the assistance apparatus 100 assists the user 1 in walking while carrying an object. That is, the assistance apparatus 100 provides walking-with-

object assistance. The input profiles corresponding to the walking-with-object assistance will be described in detail below.

Then, in step S012, the drive control unit 122 determines whether a stop instruction for stopping assistance provided by the assistance apparatus 100 has been acquired from the user 1. If the stop instruction has been acquired (Yes in step S012), the drive control unit 122 stops the operation of the assistance apparatus 100 and terminates the series of processes. If no stop instruction is acquired (No in step S012), the process returns to step S007. The stop instruction may be an instruction for changing the operation mode.

In step S010, the drive control unit 122 acquires a gait phase predicted by the gait timing detection unit 123. Then, in step S011, the drive control unit 122 controls the motors 114 on the basis of the acquired gait phase to generate tensions in the wires 110 of the assistance apparatus 100 in accordance with input profiles corresponding to "walking with no object". The input profiles in step S011 may be the same as the input profiles in step S004. In this way, the assistance apparatus 100 provides walking-with-no-object assistance to the user 1. After step S011, the drive control unit 122 proceeds to step S012.

In step S013, the drive control unit 122 determines whether the instruction indicates the lifting mode. If the instruction indicates the lifting mode (Yes in step S013), the drive control unit 122 proceeds to step S014. If the instruction does not indicate the lifting mode (No in step S013), the drive control unit 122 proceeds to step S016.

In step S014, the drive control unit 122 controls the motors 114 to generate tensions in the wire 110a2 and the wire 110a4 in accordance with input profiles corresponding to the lifting mode. The drive control unit 122 controls the tensions of the wires 110 on the basis of the tensions of the wires 110, each of which is acquired from the corresponding one of the force sensors 115, to assist the user 1 in extending each of the left and right legs. In this way, the assistance apparatus 100 assists the user 1 in performing a lifting motion. The input profiles corresponding to the lifting mode will be described in detail below.

Then, in step S015, the drive control unit 122 determines whether a stop instruction for stopping assistance provided by the assistance apparatus 100 has been acquired from the user 1. If the stop instruction has been acquired (Yes in step S015), the drive control unit 122 stops the operation of the assistance apparatus 100 and terminates the series of processes. If no stop instruction is acquired (No in step S015), the process returns to step S014. The stop instruction may be an instruction for changing the operation mode.

In step S016, the drive control unit 122 performs calibration of the assistance apparatus 100. Specifically, the control unit 120 sets a maximum tension to be generated in each of the wires 110 through input by the user 1. Thus, the maximum tensions of the wires 110 can be set in accordance with the state of the user 11 and in accordance with the muscle strengths and the like of the left and right legs of the user 1. The details of calibration will be described below.

As described above, the assistance apparatus 100 assists a user in walking with or without an object, assists the user in lifting an object, or performs calibration of the assistance apparatus 100 in accordance with the operation mode selected by the user. In the object transport walking mode, the assistance apparatus 100 changes the input profiles of tensions, each of which is generated in one of the wires 110a1 to 110a4, in accordance with whether the user is carrying an object, and assists the user in accordance with the state of the user.

3-2. Description of Operation of Assistance Apparatus in First Pattern

The operation of an assistance apparatus in a first pattern will be described. The operation in the first pattern is an operation of an assistance apparatus for assisting a user in walking when the user walks forward while neither carrying nor holding any object such as an item. The operation in the first pattern corresponds to walking-with-no-object assistance. A description will be given of a relationship in the operation in the first pattern between a wire whose tension is to be increased and the timing of increasing the tension of the wire in assistance for flexion and extension of the legs of a user who is walking forward. The operation of the assistance apparatus 100 according to the embodiment and the operation of the assistance apparatus 200 according to the modification are the same, except that the number of wires in which tensions are to be generated for assistance for flexion and extension and maximum tension values are different. Thus, the following describes the operation of the assistance apparatus 100 according to the embodiment, with no description given of the operation of the assistance apparatus 200 according to the modification. The operation in the first pattern, that is, assistance for forward walking of a user who is carrying no object, is an example of second assistance.

The drive control unit 122 of the assistance apparatus 100 determines, based on a wire-tension relationship for a type of assistance, namely, either of flexion and extension, wires in which tensions are to be generated, pulling tensions of the wires, and the timing at which and the period during which the tensions of the wires are generated, and assists motions of the user. For example, FIG. 25 illustrates an example operation of the assistance apparatus 100 for assisting a user in walking forward while carrying no object.

In FIG. 25, a relationship is illustrated among a gait state of a user, a gait phase of each leg, and the swing phase and stance phase of each leg. In the illustration of FIG. 25, the gait phase of each leg, wires in which tensions are to be generated, and the states of the tensions of the wires, that is, the input profiles of wire tensions, are associated with each other. An input profile of a wire tension represents the ratio of a wire tension to a maximum tension to be generated in each wire (also referred to as tension gain). For example, when the tension gain of each wire is 100 N, a tension to be actually generated is represented by an expression of a tension value stipulated in the input profile $\times$ tension gain. During a period of 0 to 100% of a gait phase, the assistance apparatus 100 produces a wire tension while changing the wire tension, with a maximum tension being 100 N. The maximum tension may be equal to a maximum tension set in the calibration mode described below or may be less than the maximum tension set in the calibration mode.

In the example illustrated in FIG. 25, the assistance apparatus 100 assists both flexion and extension of the left and right legs of the user. As described above, the assistance apparatus 100 generates a tension in the wire 110a1 to apply an assistance force for flexion to the left leg, and generates a tension in the wire 110a2 to apply an assistance force for extension to the left leg. The assistance apparatus 100 generates a tension in the wire 110a3 to apply an assistance force for flexion to the right leg, and generates a tension in the wire 110a4 to apply an assistance force for extension to the right leg. The assistance apparatus 100 may assist either flexion or extension of the left and right legs of the user, instead of both flexion and extension of the left and right legs of the user.

In FIG. 25, the gait phase of the right leg is used as a reference gait phase. In the gait phase of the right leg, heel strike of the right leg occurs at 0%, and heel strike of the left leg occurs at 50%. In this embodiment, as a non-limiting example, a time point of 0% of the gait phase of the right leg corresponds to a time point of 50% of the gait phase of the left leg. In the example illustrated in FIG. 25, the gait phase of the right leg is used as a reference gait phase, for convenience of illustration. The gait phase of either leg may be used as a reference gait phase, and the gait phase of one leg need not be used as a reference gait phase.

The stance phase of the right leg is a period of 0% or more and 60% or less of the gait phase of the right leg, and the swing phase of the right leg is a period of more than 60% and less than 100% of the gait phase of the right leg.

The swing phase of the left leg is a period of more than 60% and less than 100% of the gait phase of the left leg, and the stance phase of the left leg is a period of 100% or more and 160% or less of the gait phase of the left leg. In the gait phase of the left leg, a period of more than 60% and less than 100% of the gait phase of the left leg, which is the swing phase of the left leg, is included in a first gait cycle of the left leg, and a period of 100% or more and 160% or less of the gait phase of the left leg, which is the stance phase of the left leg, is included in a second gait cycle of the left leg, which is subsequent to the first gait cycle of the left leg. That is, a period of 100% or more and 160% or less of the gait phase of the left leg corresponds to a period of 0% or more and 60% or less of the second gait phase of the left leg. In the following description, a gait phase represented using a value greater than or equal to 100% means a gait phase subsequent to a gait phase represented using a value of 0% to 100%. In FIG. 25, furthermore, a gait phase represented using a value over 100% may be converted into a value of 0% to 100% and represented using the value of 0% to 100%.

When assisting the user in walking forward, for example, the assistance apparatus 100 applies an assistance force for flexion to the left leg at a timing of about 40% of the gait phase of the left leg. A timing of about 40% of the gait phase of the left leg is included in the stance phase of the left leg and the swing phase of the right leg. Specifically, a timing of about 40% of the gait phase of the left leg is a timing immediately before the right leg touches the ground during the swing phase. At this time, the center of gravity of the body of the user shifts forward. When assisting the user in walking forward, for example, the assistance apparatus 100 applies an assistance force for flexion to the right leg at a timing of about 40% of the gait phase of the right leg. A timing of about 40% of the gait phase of the right leg is included in the swing phase of the left leg and the stance phase of the right leg. Specifically, a timing of about 40% of the gait phase of the right leg is a timing immediately before the left leg touches the ground during the swing phase. At this time, the center of gravity of the body of the user shifts forward.

Further, the assistance apparatus 100 applies an assistance force for extension to the left leg at a timing of about 75% of the gait phase of the left leg, for example. A timing of about 75% of the gait phase of the left leg is included in the swing phase of the left leg and the stance phase of the right leg. Specifically, a timing of about 75% of the gait phase of the left leg is a timing in the middle of moving the left leg of the user forward during the swing phase and is included in the period during which the center of gravity of the body of the user shifts from backward to forward. Further, the assistance apparatus 100 applies an assistance force for extension to the right leg at a timing of about 75% of the gait

phase of the right leg, for example. A timing of about 75% of the gait phase of the right leg is included in the stance phase of the left leg and the swing phase of the right leg. Specifically, a timing of about 75% of the gait phase of the right leg is a timing in the middle of moving the right leg of the user forward during the swing phase and is included in the period during which the center of gravity of the body of the user shifts from backward to forward.

When assisting the user in walking forward, the assistance apparatus 100 generates a tension greater than or equal to a first threshold value in each of the wires 110a1 to 110a4. In the example illustrated in FIG. 25, the respective tensions of the wires 110a1 to 110a4 are 100 N, for example. The first threshold value may be a tension value that allows the user to recognize that flexion or extension is promoted by a tension generated in a wire. The first threshold value is, for example, 40 N, which is 40% of 100 N. In the example illustrated in FIG. 25, the assistance apparatus 100 generates a wire tension in each of the wires 110a1 to 110a4 in such a manner that the wire tension gradually increases, reaches a maximum tension, and then gradually decreases during the period of generation of the wire tension. The input profiles of the wire tensions generated in the wires 110a1 to 110a4 by the assistance apparatus 100 each exhibit a waveform that is convex curve. In this example, the maximum tension is 100 N.

To assist flexion of the left leg, for example, the assistance apparatus 100 continuously generates a tension in the wire 110a1 during the entirety of a first period, which is a period of 40% or more and 85% or less of the gait phase of the left leg. Then, the assistance apparatus 100 generates a tension greater than or equal to the first threshold value in the wire 110a1 during at least a portion of the first period. In the first period, the left leg shifts from the stance phase to the swing phase. Applying an assistance force for flexion to the left leg in the shift from the stance phase to the swing phase allows the user to easily raise the left leg and ensures that the user can easily walk.

In the example illustrated in FIG. 25, the assistance apparatus 100 generates no tension in the wire 110a1 during a fifth period, which is a period other than the first period. The fifth period may be a period of 0% or more and less than 40% of the gait phase of the left leg and a period of more than 85% and less than 100% of the gait phase of the left leg. However, the assistance apparatus 100 may generate a tension during the fifth period. For example, the assistance apparatus 100 may generate a tension less than a second threshold value in the wire 110a1 during the fifth period. The second threshold value is a tension value that is smaller than the first threshold value and that is not perceivable by the user, for example. For example, the second threshold value may be a tension value that prevents the wire 110a1 from loosening. The second threshold value is a value that is 0.2 to 0.4 times the first threshold value or is 10 N, for example. In the specification and the appended claims, generation of a tension less than the second threshold value means generation of a tension greater than or equal to 0 and less than the second threshold value and includes generation of a tension of 0.

The start timing of the first period may be included in a period of 35% or more and 55% or less of the gait phase of the left leg. The end timing of the first period may be included in a period of 80% or more and 90% or less of the gait phase of the left leg. In the example illustrated in FIG. 25, the wire tension is maximum at a timing of 65% of the gait phase of the left leg. However, the wire tension may be maximum at a time during a period of 60% or more and 70%

or less of the gait phase of the left leg. Thus, the first period may be a period of 35% or more and 90% or less of the gait phase of the left leg.

To assist extension of the left leg, for example, the assistance apparatus 100 continuously generates a tension in the wire 110a2 during the entirety of a second period, which is a period of 75% or more and 120% or less of the gait phase of the left leg. Then, the assistance apparatus 100 generates a tension greater than or equal to the first threshold value in the wire 110a2 during at least a portion of the second period. In the second period, the left leg shifts from the swing phase to the stance phase. Applying an assistance force for extension to the left leg in the shift from the swing phase to the stance phase allows the left leg of the user to touch the ground stably and ensures that the user can easily walk. In the example illustrated in FIG. 25, the assistance apparatus 100 generates no tension in the wire 110a2 during a sixth period, which is a period other than the second period. The sixth period may be a period of more than 20% and less than 75% of the gait phase of the left leg. However, the assistance apparatus 100 may generate a tension less than the second threshold value during the sixth period.

The start timing of the second period may be included in a period of 65% or more and 90% or less of the gait phase of the left leg. The end timing of the second period may be included in a period of 110% or more and 125% or less of the gait phase of the left leg. In the example illustrated in FIG. 25, the wire tension is maximum at a timing of 100% of the gait phase of the left leg. However, the wire tension may be maximum at a time during a period of 85% or more and 100% or less of the gait phase of the left leg. Thus, the second period may be a period of 65% or more and 125% or less of the gait phase of the left leg, that is, may include a period of 0% or more and 25% or less of the gait phase of the left leg and a period of 65% or more and less than 100% of the gait phase of the left leg.

To assist flexion of the right leg, for example, the assistance apparatus 100 continuously generates a tension in the wire 110a3 during the entirety of a third period, which is a period of 40% or more and 85% or less of the gait phase of the right leg. Then, the assistance apparatus 100 generates a tension greater than or equal to the first threshold value in the wire 110a3 during at least a portion of the third period. In the third period, the right leg shifts from the stance phase to the swing phase. In the example illustrated in FIG. 25, the assistance apparatus 100 generates no tension in the wire 110a3 during a seventh period, which is a period other than the third period. However, the assistance apparatus 100 may generate a tension less than the second threshold value during the seventh period. The seventh period may be a period of 0% or more and less than 40% of the gait phase of the right leg and a period of more than 85% and less than 100% of the gait phase of the right leg.

The start timing of the third period may be included in a period of 35% or more and 55% or less of the gait phase of the right leg. The end timing of the third period may be included in a period of 80% or more and 90% or less of the gait phase of the right leg. In the example illustrated in FIG. 25, the wire tension is maximum at a timing of 65% of the gait phase of the right leg. However, the wire tension may be maximum at a time during a period of 60% or more and 70% or less of the gait phase of the right leg. Thus, the third period may be a period of 35% or more and 90% or less of the gait phase of the right leg.

To assist extension of the right leg, for example, the assistance apparatus 100 continuously generates a tension in the wire 110a4 during the entirety of a fourth period, which

is a period of 75% or more and 120% or less of the gait phase of the right leg. Then, the assistance apparatus 100 generates a tension greater than or equal to the first threshold value in the wire 110a4 during at least a portion of the fourth period. In the fourth period, the right leg shifts from the swing phase to the stance phase. In the example illustrated in FIG. 25, the assistance apparatus 100 generates no tension in the wire 110a4 during an eighth period, which is a period other than the fourth period. However, the assistance apparatus 100 may generate a tension less than the second threshold value during the eighth period.

The start timing of the fourth period may be included in a period of 65% or more and 90% or less of the gait phase of the right leg. The end timing of the fourth period may be included in a period of 110% or more and 125% or less of the gait phase of the right leg. In the example illustrated in FIG. 25, the wire tension is maximum at a timing of 100% of the gait phase of the right leg. However, the wire tension may be maximum at a time during a period of 85% or more and 100% or less of the gait phase of the right leg. Thus, the fourth period may be a period of 65% or more and 125% or less of the gait phase of the right leg, that is, may include a period of 0% or more and 25% or less of the gait phase of the right leg and a period of 65% or more and less than 100% of the gait phase of the right leg.

As described above, during the entirety of a period corresponding to each input profile of a wire tension, the assistance apparatus 100 continuously generates a tension in the wire corresponding to the input profile. However, the embodiment is not limited to this. The assistance apparatus 100 may temporarily stop the generation of the tension in the wire during the period corresponding to the input profile. In this case, a load imposed on the leg of the user by the assistance apparatus 100 is reduced, and the load felt by the user on which the assistance apparatus 100 acts is reduced.

The input profiles of wire tensions illustrated in FIG. 25 are set so that the tension of each wire rises earlier than a desired time point by several percent (%) of the gait phase in consideration of a time delay from when the drive control unit 122 outputs a signal to the corresponding motor to when a tension is actually generated in the wire. For example, in the example illustrated in FIG. 25, input profiles of wire tensions are created so that the tension of each wire rises earlier than a desired time point by approximately 5%. For assistance for flexion, the assistance apparatus 100 provides assistance so that the assistance for flexion is completed immediately before the heel strikes the ground. Thus, input profiles of wire tensions are created so that assistance for flexion ends at a time during a period of 80% or more and 90% or less of the gait phase of the each leg in order to complete assistance for flexion at a timing of about 100% of the gait phase of each leg in consideration of a delay of output of the tension of each wire.

3-3. Description of Operation of Assistance Apparatus in Second Pattern

The operation of the assistance apparatus 100 in a second pattern will be described. The operation in the second pattern is an operation of the assistance apparatus 100 for assisting a user in walking when the user walks forward while carrying an object. The operation in the second pattern corresponds to walking-with-object assistance. For example, FIG. 26 illustrates an example operation of the assistance apparatus 100 for assisting a user in walking forward while carrying an object. In the example illustrated in FIG. 26, the assistance apparatus 100 assists both flexion and extension of the left and right legs of the user. The assistance apparatus 100 produces a wire tension while changing the wire ten-

sion, with a maximum tension being 100 N. The maximum tension may be equal to a maximum tension set in the calibration mode described below or may be less than the maximum tension set in the calibration mode. The operation in the second pattern, that is, assistance for forward walking of a user who is carrying an object, is an example of first assistance.

When assisting flexion of a user during forward walking with an object, the assistance apparatus **100** generates wire tensions in the wire **110a1** of the left leg and the wire **110a3** of the right leg in a way similar to that for a user during forward walking while carrying no object described above.

When assisting extension of the left leg, for example, the assistance apparatus **100** continuously generates a tension in the wire **110a2** during the entirety of a second period, which is a period of 75% or more and 120% or less of the gait phase of the left leg. Then, the assistance apparatus **100** generates a wire tension greater than or equal to the first threshold value in the wire **110a2** during at least a portion of the second period. Then, the assistance apparatus **100** continuously generates a tension greater than or equal to the second threshold value and less than or equal to a sixth threshold value in the wire **110a2** during the entirety of a sixth period, which is a period other than the second period. The sixth period may be a period of more than 20% and less than 75% of the gait phase of the left leg. The tension of the wire **110a2** in the sixth period is greater than the tension of the wire **110a1** in the fifth period and is greater than the tension of the wire **110a2** in the sixth period during the operation in the first pattern. Then, the assistance apparatus **100** continuously generates a tension greater than the wire tension in the sixth period in the wire **110a2** during the entirety of the second period. Thus, the assistance apparatus **100** continuously generates a tension greater than or equal to the second threshold value in the wire **110a2** during an entire period including the second period and the sixth period. The sixth threshold value is a value less than the maximum wire tension. The sixth threshold value is, for example, a value given by an expression of maximum tension $\times 0.6$.

When assisting extension of the right leg, for example, the assistance apparatus **100** continuously generates a tension in the wire **110a4** during the entirety of a fourth period, which is a period of 75% or more and 120% or less of the gait phase of the right leg. Then, the assistance apparatus **100** generates a wire tension greater than or equal to the first threshold value in the wire **110a4** during at least a portion of the fourth period. Then, the assistance apparatus **100** continuously generates a tension greater than or equal to the second threshold value and less than or equal to the sixth threshold value in the wire **110a4** during the entirety of an eighth period, which is a period other than the fourth period. The eighth period may be a period of more than 20% and less than 75% of the gait phase of the right leg. The tension of the wire **110a4** in the eighth period is greater than the tension of the wire **110a3** in the seventh period and is greater than the tension of the wire **110a4** in the eighth period during the operation in the first pattern. Then, the assistance apparatus **100** continuously generates a tension greater than the wire tension in the eighth period in the wire **110a4** during the entirety of the fourth period. Thus, the assistance apparatus **100** continuously generates a tension greater than or equal to the second threshold value in the wire **110a4** during an entire period including the fourth period and the eighth period.

As described above, a tension greater than or equal to the second threshold value is generated in the wires **110a2** and **110a4**, which are located on or above the back part of the body of the user, during the entirety of a period over which

the assistance apparatus **100** provides assistance. Thus, the user is subjected to the action such that the left and right legs are pulled backward all the time during walking. When the user is holding an object in the front part of the body, the center of gravity of the body of the user tends to be moved forward. Thus, the user, who is holding an object in the front part of the body, is subjected to the action such that the tensions of the wires **110a2** and **110a4** cause the user to walk forward with the center of gravity being kept at the center of gravity position in the upright posture. This enables the user to walk with a stable posture. Accordingly, the user is able to transport an object with comfort. In the fifth period, the tension of the wire **110a1** for assisting flexion of the left leg is small, and thus the action exerted by the tension of the wire **110a2** is achieved while being less affected by the tension of the wire **110a1**. In the seventh period, the tension of the wire **110a3** for assisting flexion of the right leg is small, and thus the action exerted by the tension of the wire **110a4** is achieved while being less affected by the tension of the wire **110a3**.

The assistance apparatus **100** may perform the operation in the second pattern so as to prevent the user from stumbling. By preventing the user from stumbling, the assistance apparatus **100** can prevent the user from falling. In this case, for example, the assistance apparatus **100** generates substantially no wire tension, that is, a wire tension less than the second threshold value, in the wire **110a2** for assisting extension of the left leg during a portion of the sixth period corresponding to the swing phase of the left leg in the gait phase of the left leg. This period is, for example, a period of more than 60% and less than 75% of the gait phase of the left leg. Likewise, the assistance apparatus **100** generates a tension less than the second threshold value in the wire **110a4** for assisting extension of the right leg during a portion of the eighth period corresponding to the swing phase of the right leg in the gait phase of the right leg. This period is, for example, a period of more than 60% and less than 75% of the gait phase of the right leg. This enables the user to easily raise a leg off the ground and prevents the user from dragging the toe on the ground, level differences, or the like when raising the leg.

Further, for example, the assistance apparatus **100** continuously generates a wire tension greater than or equal to the second threshold value and less than or equal to the sixth threshold value in the wire **110a1** for assisting flexion of the left leg during the entirety of the fifth period in the gait phase of the left leg. The tension of the wire **110a1** in the fifth period is greater than the tension of the wire **110a1** in the fifth period during the operation in the first pattern. This enables the user to easily raise the left leg in the shift to flexion in the first period. Further, the assistance apparatus **100** continuously generates a wire tension greater than or equal to the second threshold value and less than or equal to the sixth threshold value in the wire **110a3** for assisting flexion of the right leg during the entirety of the seventh period in the gait phase of the right leg. The tension of the wire **110a3** in the seventh period is greater than the tension of the wire **110a3** in the seventh period during the operation in the first pattern. This enables the user to easily raise the right leg in the shift to flexion in the third period. Accordingly, the assistance apparatus **100** allows the user to easily raise a leg during flexion and prevents the user from dragging the toe and stumbling.

3-4. Description of Operation of Assistance Apparatus in Third Pattern

The operation of the assistance apparatus **100** in a third pattern will be described. The operation in the third pattern

is an operation of assisting a stationary user in lifting an object. For example, FIG. 27 illustrates an example operation of the assistance apparatus 100 for assisting a stationary user in lifting an object. The assistance apparatus 100 produces a wire tension while changing the wire tension, with a maximum tension being 100 N. The maximum tension may be equal to a maximum tension set in the calibration mode described below or may be less than the maximum tension set in the calibration mode. The operation in the third pattern is an example of third assistance.

In the operation in the third pattern, the assistance apparatus 100 does not assist flexion of the left and right legs, but assists extension of the left and right legs. For example, as illustrated in FIG. 5B, when lifting an object in front of the user, the user shifts from a stooping or crouching position to an upright position. At this time, the state of the left and right legs of the user transitions from the state of flexion of the knees and hip joints to the state of extension of the knees and hip joints. The user, who receives an assistance force for extension of both legs from the assistance apparatus 100, facilitates the shift between the states described above.

As illustrated in FIG. 27, when assisting the user in performing a lifting motion, the assistance apparatus 100 generates a tension greater than a fifth threshold value in the wires 110a2 and 110a4 at the same timing. The fifth threshold value is a value larger than the first threshold value and the second threshold value. The fifth threshold value is, for example, 60 N. The tensions of the wires 110a2 and 110a4 for assisting the user in lifting an object may be greater than the tensions of the wires 110a1 to 110a4 for assisting the user in walking forward while carrying an object.

Upon receipt of an instruction for implementing the lifting mode from the input device 140 of the assistance apparatus 100, the terminal device 150, or the like at time point P1, the drive control unit 122 starts the generation of tensions in the wires 110a2 and 110a4 at the same timing. The drive control unit 122 gradually increases the tensions to be generated in the wires 110a2 and 110a4 to a predetermined maximum tension greater than the fifth threshold value. When the tensions of the wires 110a2 and 110a4 reach the maximum tension, the drive control unit 122 keeps the tensions of the wires 110a2 and 110a4 at the maximum tension. The maximum tension may be greater than the maximum tension in the operation in the first pattern and the maximum tension in the operation in the second pattern. The term "same timing" is used to include not only exactly the same timing but also different timings or timings with a difference.

Thus, while receiving an assistance force from the assistance apparatus 100, the user stands up with the left leg extended from the state in which the knee and the hip joint are flexed and with the right leg extended from the state in which the knee and the hip joint are flexed, and changes from the stooping posture to the upright posture. Upon receipt of an instruction at time point P2 for stopping assistance from the user, who no longer desires assistance, the drive control unit 122 gradually decreases the tensions generated in the wires 110a2 and 110a4 to a tension less than the second threshold value at time point P3. In the illustrated example, the period from the time point P1 to the time point at which the wire tension reaches the maximum tension is shorter than the period from the time point P2 to the time point P3. However, the embodiment is not limited to this example. In the illustrated example, furthermore, the drive control unit 122 sets the tensions of the wires 110a2 and 110a4 to 0 N as a tension less than the second threshold value. However, the embodiment is not limited to this example.

The drive control unit 122 generates tensions in the wires 110a2 and 110a4 over the period from the time point P1 to the time point P3 in accordance with a trapezoidal input profile waveform. In this case, the wires 110a2 and 110a4 have the same maximum tension and the same input profile waveform. This enables the user to lift an object while receiving balanced assistance forces at the left and right legs.

The tensions of the wires 110a2 and 110a4 may be generated at timings that are shifted with respect to each other. Further, the waveforms of the input profiles of the tensions of the wires 110a2 and 110a4 may be different. Further, the maximum tensions to be generated in the wires 110a2 and 110a4 may be different. For example, when the states of the left and right legs are different, such as when only the knee of one of the left and right legs is in contact with the floor surface, the timings of generation of the tensions of the wires 110a2 and 110a4, the maximum tensions of the wires 110a2 and 110a4, and the waveforms of the input profiles of the tensions of the wires 110a2 and 110a4 may differ based on a difference between the timings at which loads on the left and right legs are generated, a difference in magnitude between the loads on the left and right legs, and so on. In addition, the wires 110a2 and 110a4 may have different maximum tensions and input profile waveforms in accordance with a difference in muscle strength between the left and right legs of the user.

3-5. Modification of Operation of Assistance Apparatus

In the respective operations of the assistance apparatuses 100 and 200 according to the embodiment and the modification, the same input profile of wire tension and the same maximum wire tension are set for all the wires 110 for assisting flexion and extension. However, the present disclosure is not limited to the embodiment and the modification described above. Since the moment arms of the hip joints and the lengths of the legs differ from one user to another, the assistance torque exerted on the hip joint differs depending on the user even when the same tension is applied to the same wire. The assistance torque is determined by an expression of wire tension $\times$ moment arm. Thus, different tensions may be applied to wires in accordance with the user. A fatter user has a larger moment arm of the hip joint than a thinner user. Thus, for example, the maximum wire tension may be set to 60 N for a fat user with a girth of 100 cm or more, whereas the maximum wire tension may be set to 120 N for a thin user with a girth of 70 cm or less. This may make assistance torques exerted on a fat user and a thin user equivalent.

In addition, the wire tension may change in accordance with the lengths of the legs of the user. In assistance for flexion and extension, since a vertical, or upward and downward, force component of wire tension is more largely exerted on a user with longer legs, the wire tension for a user with longer legs may be reduced. Adjusting the wire tension for each user in accordance with the body type and the leg length enables a comfortable assistance torque to be applied to each user.

In addition, the wire tensions on the front and back sides of the legs of the user are set to the same value. However, the present disclosure is not limited to the embodiment and the modification described above. For example, the tensions of the wires located on the front side of the legs may be greater than the tensions of the wires located on the back side of the legs. Since the wires on the back side pass through the buttocks of the user, the moment arm on the back side of the body of the user is greater than that on the front side of the body of the user. Accordingly, the assistance torque exerted on the hip joints on the back side of the body

of the user is greater than that on the front side of the body of the user. Thus, by increasing the tension of the wires on the front side, the assistance apparatuses **100** and **200** can assist flexion and extension of the user on the front and back sides in a well-balanced manner.

The periods during which wire tensions are generated in the wires **110** for assistance for flexion and extension are equal to each other. However, the present disclosure is not limited to the embodiment and the modification described above. For example, in the example illustrated in FIG. 25, the period during which a wire tension for assisting flexion is generated and the period during which a wire tension for assisting extension of the same leg is generated overlap. To reduce the overlap period, the length of either of the periods may be reduced. In particular, the periods may be adjusted such that the period in which a wire tension greater than or equal to the first threshold value is generated during assistance for flexion does not overlap the period in which a wire tension greater than or equal to the first threshold value is generated during assistance for extension. This also applies to the example illustrated in FIG. 26. This prevents the user from being confused by the simultaneous feeling of assistance for flexion and assistance for extension. The relationship between the period during which a wire tension for assisting flexion is generated and the period during which a wire tension for assisting extension is generated may be determined in accordance with the flexion and extension ability of the user.

In FIG. 25 and FIG. 26, the waveforms of the input profiles of wire tensions are convex curve. However, the present disclosure is not limited to the illustrated examples. The waveforms of the input profiles illustrated in FIG. 25 and FIG. 26 are waveforms obtained through experiments, which are waveforms that allow users to feel effective and comfortable when enjoying the benefits of assistance provided by the assistance apparatus **100**. The input profiles of the wire tensions may be each created using, for example, a rectangular waveform, a trapezoidal waveform, a triangular waveform, a Gaussian waveform, or the like. When a rectangular waveform is used, the assistance apparatus **100** continuously generates a maximum tension during an entire period over which a wire tension is generated. When a trapezoidal waveform is used, the assistance apparatus **100** continuously generates a maximum tension during an entire period over which a wire tension is generated, except the initial and terminal periods. When each input profile is created using a waveform that is quadrangle such as a rectangular waveform and a trapezoidal waveform, a steep rise or a steep fall of the wire tension may occur. Such a change in tension may cause a user to feel uncomfortable during assistance. Thus, for example, when the waveform of each input profile is triangular, a rise of the wire tension to the maximum tension may be changed to a gentler one, with the wire tension changing gradually. Accordingly, the assistance apparatus **100** can carefully assist movements of the legs of the user, resulting in a reduction in the risk of falling of the user due to a steep change in wire tension.

In actual human walking, flexion and extension torques produced by the legs smoothly and continuously change. Thus, the waveform of each input profile may be implemented as a Gaussian waveform. The Gaussian waveform may be a waveform created by, for example, adding together, or superposing, Gaussian functions by using a Gaussian function given by Equation (1) below. In this case, among superposition methods of Gaussian functions, a superposition method that is closest to the waveform of a torque of the legs in actual human walking is found and

applied to the generation of a waveform of an input profile. Finding such a method is also referred to as Gaussian fitting. Accordingly, assistance torques can be applied to realize walking similar to actual human walking, and more natural assistance can be achieved.

$$f(x) = \frac{1}{\sqrt{2\pi}\sigma} \exp\left\{-\frac{(x-\mu)^2}{2\sigma^2}\right\} \quad (1)$$

10

Specifically, a Gaussian function has a pair of variables μ and σ (also referred to as parameters), and the waveform of the Gaussian function depends on the two parameters. The time indicating a peak of a wave of the Gaussian function depends on the variable μ , and the width of the wave of the Gaussian function depends on the variable σ . Thus, various Gaussian functions may be generated by using various combinations of values of the two parameters.

20 A function obtained by multiplying an amplitude of a torque generated in a leg during human walking by a Gaussian function forms a waveform that shows time (in seconds) on the horizontal axis and torque (in Nm) on the vertical axis. Examples of the amplitude include a maximum torque of a leg during human walking, and the amplitude is, for example, 20 Nm. Gaussian functions are superposed to find a superposition method that is closest to the torque-time waveform of the leg during actual human walking. At this time, Gaussian fitting is performed on actual human gait data by using n Gaussian functions $f_1(x)$, $f_2(x)$, ..., and $f_n(x)$ having various values of the two parameters μ and σ to obtain Gaussian functions. The obtained Gaussian functions are further superposed to obtain a new Gaussian function. 25 By adjusting the two parameters μ and σ of the new Gaussian function, an input profile of a wire tension can be created.

30 Further, the assistance apparatus **100** may change the maximum tensions to be generated in the wires **110** in accordance with the time of year when the user wears the assistance apparatus **100**. For example, in summer when the user wears light clothes, the user's moment arm is shorter than that in winter when the user wears thick clothes. Accordingly, even when the assistance apparatus **100** applies the same tensions to the wires **110**, the torques exerted on the legs of the user are smaller than those in winter. Thus, for example, the assistance apparatus **100** may increase the tension to be applied to each of the wires **110** in summer to, for example, 1.2 times that in winter.

35 The operation of the assistance apparatus **200** according to the modification illustrated in FIG. 13 to FIG. 21 is also similar to that of the assistance apparatus **100** according to the embodiment. For the operations described above, the 40 wire tension control for the first wire **110a1** and the wire tension control for the fifth wire **110a5** of the assistance apparatus **200** are similar to the wire tension control for the wire **110a1** of the assistance apparatus **100**. The wire tension control for the second wire **110a2** and the wire tension control for the sixth wire **110a6** of the assistance apparatus **200** are similar to the wire tension control for the wire **110a2** of the assistance apparatus **100**. The wire tension control for the third wire **110a3** and the wire tension control for the seventh wire **110a7** of the assistance apparatus **200** are 45 similar to the wire tension control for the wire **110a3** of the assistance apparatus **100**. The wire tension control for the fourth wire **110a4** and the wire tension control for the eighth

wire **110a8** of the assistance apparatus **200** are similar to the wire tension control for the wire **110a4** of the assistance apparatus **100**.

When assisting flexion or extension, the assistance apparatus **200** generates tensions in two wires of the same leg at the same timing. Thus, the maximum tension to be generated in the first wire **110a1** and the maximum tension to be generated in the fifth wire **110a5** of the assistance apparatus **200** may be different from the maximum tension to be generated in the wire **110a1** of the assistance apparatus **100** and may be smaller than the maximum tension to be generated in the wire **110a1** of the assistance apparatus **100**, for example. The maximum tension to be generated in the second wire **110a2** and the maximum tension to be generated in the sixth wire **110a6** of the assistance apparatus **200** may be different from the maximum tension to be generated in the wire **110a2** of the assistance apparatus **100** and may be smaller than the maximum tension to be generated in the wire **110a2** of the assistance apparatus **100**, for example. The maximum tension to be generated in the third wire **110a3** and the maximum tension to be generated in the seventh wire **110a7** of the assistance apparatus **200** may be different from the maximum tension to be generated in the wire **110a3** of the assistance apparatus **100** and may be smaller than the maximum tension to be generated in the wire **110a3** of the assistance apparatus **100**, for example. The maximum tension to be generated in the fourth wire **110a4** and the maximum tension to be generated in the eighth wire **110a8** of the assistance apparatus **200** may be different from the maximum tension to be generated in the wire **110a4** of the assistance apparatus **100** and may be smaller than the maximum tension to be generated in the wire **110a4** of the assistance apparatus **100**, for example.

The relationship between the maximum tension to be generated in the first wire **110a1** and the maximum tension to be generated in the fifth wire **110a5** of the assistance apparatus **200** and the maximum tension to be generated in the wire **110a1** of the assistance apparatus **100** changes in accordance with the angle between the direction in which the wire **110a1** of the assistance apparatus **100** extends and the direction in which the first wire **110a1** of the assistance apparatus **200** extends and in accordance with the angle between the direction in which the wire **110a1** of the assistance apparatus **100** extends and the direction in which the fifth wire **110a5** of the assistance apparatus **200** extends, and can be determined in accordance with the angles. The relationship between the maximum tension to be generated in the second wire **110a2** and the maximum tension to be generated in the sixth wire **110a6** of the assistance apparatus **200** and the maximum tension to be generated in the wire **110a2** of the assistance apparatus **100** changes in accordance with the angle between the direction in which the wire **110a2** of the assistance apparatus **100** extends and the direction in which the second wire **110a2** of the assistance apparatus **200** extends and in accordance with the angle between the direction in which the wire **110a2** of the assistance apparatus **100** extends and the direction in which the sixth wire **110a6** of the assistance apparatus **200** extends, and can be determined in accordance with the angles. The relationship between the maximum tension to be generated in the third wire **110a3** and the maximum tension to be generated in the seventh wire **110a7** of the assistance apparatus **200** and the maximum tension to be generated in the wire **110a3** of the assistance apparatus **100** changes in accordance with the angle between the direction in which the wire **110a3** of the assistance apparatus **100** extends and the direction in which the third wire **110a3** of the assistance apparatus **200** extends

and in accordance with the angle between the direction in which the wire **110a3** of the assistance apparatus **100** extends and the direction in which the seventh wire **110a7** of the assistance apparatus **200** extends, and can be determined in accordance with the angles. The relationship between the maximum tension to be generated in the fourth wire **110a4** and the maximum tension to be generated in the eighth wire **110a8** of the assistance apparatus **200** and the maximum tension to be generated in the wire **110a4** of the assistance apparatus **100** changes in accordance with the angle between the direction in which the wire **110a4** of the assistance apparatus **100** extends and the direction in which the fourth wire **110a4** of the assistance apparatus **200** extends and in accordance with the angle between the direction in which the wire **110a4** of the assistance apparatus **100** extends and the direction in which the eighth wire **110a8** of the assistance apparatus **200** extends, and can be determined in accordance with the angles.

The term "same timing" is used to include not only exactly the same timing but also different timings or timings with a difference. The difference may be less than 10% or may be 5% or less in terms of the value of the gait phase. For example, when the difference is 5% or less, the values at all timings in the gait phase are included in a range of values of the gait phase, which is within $\pm 5\%$ from an average value of values at the timings in the gait phase.

3-6. Description of Calibration Operation of Assistance Apparatus

The calibration operation of the assistance apparatus **100** will be described. The calibration operation is an operation for setting a maximum tension to be generated in each wire. In this embodiment, the assistance apparatus **100** uses a change in the tension of each wire to indicate items to be notified to the user, such as items presented during the calibration operation, response results, and determined items. That is, the assistance apparatus **100** notifies the user of various kinds of information by causing the user to feel bodily sensations.

For example, FIG. 28 illustrates an example flow of a calibration operation performed by the assistance apparatus **100**. As illustrated in FIG. 28, first, in step S101, the drive control unit **122** of the assistance apparatus **100** acquires an instruction from a user to implement the calibration mode through the input device **140**, the terminal device **150**, or the like.

Then, in step S102, the drive control unit **122** notifies the user of the determination of the implementation of the calibration mode, by using bodily sensations. Specifically, the drive control unit **122** simultaneously continuously generates a first tension in the wires **110a1** to **110a4** over a first predetermined time period. In this embodiment, the first tension is greater than or equal to a seventh threshold value and less than or equal to a maximum tension. The seventh threshold value is preferably a relatively large value that allows the user to clearly recognize a tension generated in a wire without awareness of the wire. The seventh threshold value is a value given by an expression of possible maximum tension $\times 0.4$ or is 40 N, for example. The first tension is, for example, a tension greater than or equal to 40 N and less than or equal to 100 N. The first predetermined time period is preferably relatively long that allows the user to clearly recognize a tension generated in a wire without awareness of the wire. The first predetermined time period is, for example, 3 seconds. Then, the drive control unit **122** starts the calibration operation.

Then, in step S103, the drive control unit **122** determines whether the setting of the maximum tension of the second

wire **110a2** is uncompleted. If the setting is uncompleted (Yes in step **S103**), the drive control unit **122** proceeds to step **S104**. If the setting has been completed (No in step **S103**), the drive control unit **122** proceeds to step **S107**.

In step **S104**, the drive control unit **122** notifies the user of a wire for which the maximum tension is to be determined. Specifically, the drive control unit **122** notifies the user of the second wire **110a2**. At this time, the drive control unit **122** intermittently generates a second tension in the second wire **110a2** at intervals of a second predetermined time period. In this embodiment, the second tension is less than the first tension. The second tension is greater than or equal to an eighth threshold value and less than the first tension. The eighth threshold value preferably has a relatively small value that allows the user to clearly recognize a tension generated in a wire when the user is aware of the wire, but that keeps the load on the user low. The eighth threshold value is a value given by an expression of possible maximum tension $\times 0.2$ or is 20 N, for example. The second tension is, for example, a tension greater than or equal to 20 N and less than or equal to 30 N. The second predetermined time period is preferably shorter than the first predetermined time period so as to differentiate notification in step **S104** from that in step **S102** for providing a determination notification. The second predetermined time period is, for example, 1 second. In this way, the drive control unit **122** repeatedly performs a 1-second continuous generation of the second tension on the second wire **110a2** at intervals of 1 second. The use of such a short second predetermined time period reduce the load on the user.

Then, in step **S105**, the user performs an operation of determining the maximum tension of the second wire **110a2**. The tension generated in step **S104** allows the user to perceive that the assistance apparatus **100** prompts the setting of the maximum tension of the second wire **110a2**. At this time, the assistance apparatus **100** can change the magnitude of the tension generated in the second wire **110a2** in accordance with the input of the user to the input device **140** or the terminal device **150**. Accordingly, the user increases or decreases the tension being generated in the second wire **110a2** by, for example, operating the “down” button **145** and the “up” button **146** of the input device **140**. As a result, the assistance apparatus **100** intermittently generates the changed tension in the second wire **110a2** at intervals of the second predetermined time period. When the user feels the tension of the second wire **110a2** reaching a tension suitable for the user, the user continuously presses the “set” button **144** of the input device **140** for a third predetermined time period or longer. Thus, the drive control unit **122** receives an instruction for determining setting the tension described above as the maximum tension of the second wire **110a2**. Upon receipt of the instruction, the drive control unit **122** determines the tension described above as the maximum tension of the second wire **110a2** and stores the determination result in the storage unit **125**.

The third predetermined time period is preferably a relatively long time period to prevent an instantaneous contact on the “set” button **144** from being received as an instruction. The third predetermined time period is, for example, 3 seconds. The tension suitable for the user may be a tension selected, as desired, by the user, such as a maximum tension endurable by the user or a maximum tension that will not impose an excessive load on the user. The user may operate the terminal device **150** having similar functions to determine the maximum tension of the second wire **110a2** while increasing or decreasing the tension being generated in the second wire **110a2**.

Then, in step **S106**, the drive control unit **122** notifies the user of the completion of the determination of the maximum tension of the second wire **110a2**. Specifically, the drive control unit **122** generates the determined maximum tension in the second wire **110a2** over a fourth predetermined time period. The fourth predetermined time period for providing a determination notification is preferably longer than the second predetermined time period so as to differentiate notification in step **S106** from that in step **S104**, and is, for example, 3 seconds, which is similar to the first predetermined time period. After step **S106**, the drive control unit **122** returns to step **S103**.

In step **S107**, the drive control unit **122** determines whether the setting of the maximum tension of the fourth wire **110a4** is uncompleted. If the setting is uncompleted (Yes in step **S107**), the drive control unit **122** proceeds to step **S108**. If the setting has been completed (No in step **S107**), the drive control unit **122** proceeds to step **S111**.

In steps **S108** to **S110**, the drive control unit **122** performs a process on the fourth wire **110a4**, which is similar to the process performed on the second wire **110a2** in steps **S104** to **S106**, to determine the maximum tension of the fourth wire **110a4**, and stores the maximum tension of the fourth wire **110a4** in the storage unit **125**. Then, the drive control unit **122** notifies the user of the completion of the determination of the maximum tension. After step **S110**, the drive control unit **122** returns to step **S107**.

Then, in step **S111**, the drive control unit **122** determines whether the setting of the maximum tension of the third wire **110a3** is uncompleted. If the setting is uncompleted (Yes in step **S111**), the drive control unit **122** proceeds to step **S112**. If the setting has been completed (No in step **S111**), the drive control unit **122** proceeds to step **S115**.

In steps **S112** to **S114**, the drive control unit **122** performs a process on the third wire **110a3**, which is similar to the process performed on the second wire **110a2** in steps **S104** to **S106**, to determine the maximum tension of the third wire **110a3**, and stores the maximum tension of the third wire **110a3** in the storage unit **125**. Then, the drive control unit **122** notifies the user of the completion of the determination of the maximum tension. After step **S114**, the drive control unit **122** returns to step **S111**.

Then, in steps **S115** to **S117**, the drive control unit **122** determines the maximum tension of the first wire **110a1**. At this time, the drive control unit **122** performs a process on the first wire **110a1**, which is similar to the process performed on the second wire **110a2** in steps **S104** to **S106**, and stores the determined maximum tension of the first wire **110a1** in the storage unit **125**. Then, the drive control unit **122** notifies the user of the completion of the determination of the maximum tension. After step **S117**, the drive control unit **122** proceeds to step **S118**.

Then, in step **S118**, the drive control unit **122** notifies the user of the completion of the determination of the maximum tensions of all the first to fourth wires **110a1** to **110a4**. Specifically, the drive control unit **122** notifies the user of the determined maximum tensions of the first to fourth wires **110a1** to **110a4**. At this time, the drive control unit **122** continuously generates the respective maximum tensions in the second wire **110a2**, the fourth wire **110a4**, the third wire **110a3**, and the first wire **110a1**, in this order, over a fifth predetermined time period. The fifth predetermined time period for providing a determination notification is preferably longer than the second predetermined time period for clarifying a wire so as to differentiate the fifth predetermined time period from the second predetermined time period. The fifth predetermined time period is, for example, 3 seconds,

which is similar to the first predetermined time period. An interval, which is a time period during which no tension is generated in any wire, may be provided between time periods over which maximum tensions are generated in different wires.

As described above, the drive control unit 122 sequentially determines maximum tensions for the first to fourth wires 110a1 to 110a4 while causing the user to actually feel bodily sensations of wire tensions, and further sequentially notifies the user of the determined maximum tensions by using bodily sensations. The order in which the maximum tensions of the first to fourth wires 110a1 to 110a4 are determined is not limited to that described above, and the maximum tensions of the first to fourth wires 110a1 to 110a4 may be determined in any order.

3-7. Modification of Calibration Operation of Assistance Apparatus

The wire control performed by the assistance apparatus 100 during the calibration operation is not limited to that described above, and the assistance apparatus 100 may perform any control so long as the user can be notified of information by experiencing bodily sensations in each step.

For example, in steps S104, S108, S112, and S115 in FIG. 28, to notify the user of a wire for which the maximum tension is to be determined, the drive control unit 122 intermittently generates the second tension in the wire at intervals of the second predetermined time period. The number of times the second tension is to be generated may be determined. For example, the drive control unit 122 generates the second tension in the wire a second predetermined number of times at intervals of the second predetermined time period. The second predetermined number of times is, for example, three, which makes it easy for the user to perform recognition.

Further, in steps S105, S109, S113, and S116 in FIG. 28, when the user performs an operation of determining the maximum tension of each wire, the drive control unit 122 intermittently generates a tension, which is changed in accordance with the input to the input device 140 or the terminal device 150, in the wire at intervals of the second predetermined time period. However, the drive control unit 122 may continuously generate the changed tension in each wire.

Further, in step S118 in FIG. 28, to notify the user the completion of the determination of the maximum tensions of all the wires, the drive control unit 122 sequentially generates the determined maximum tensions in the respective wires. However, the drive control unit 122 may generate, in all the corresponding wires, the respective determined maximum tensions at the same timing. Then, the drive control unit 122 continuously generates the maximum tensions over a sixth predetermined time period, which is longer than the second predetermined time period. The sixth predetermined time period is, for example, 3 seconds, which is similar to the first predetermined time period.

3-8. Description of Operation for Determining Operation Mode of Assistance Apparatus

The operation of the assistance apparatus 100 for selecting each operation mode and determining implementation of the operation mode will be described. When power is turned on and the assistance apparatus 100 is started, the assistance apparatus 100 prompts the user to select each operation mode by using the input device 140. For example, when the user continuously presses the "mode" button 143 of the input device 140 for a seventh predetermined time period or longer after the start of the assistance apparatus 100, the assistance apparatus 100 enters an operation selection mode

for prompting the user to select each operation mode and determining implementation of the operation mode. The seventh predetermined time period is, for example, 3 seconds, which is similar to the third predetermined time period.

The assistance apparatus 100 generates a tension in each wire to prompt the user to select each operation mode by using bodily sensations. Specifically, the assistance apparatus 100 generates a tension in each wire in accordance with 10 a tension generation pattern corresponding to each operation mode to sequentially clarify the corresponding operation mode. For example, immediately after the start of the operation selection mode, the assistance apparatus 100 generates a tension in each wire in accordance with the generation pattern corresponding to the normal walking mode to clarify the normal walking mode. To select the normal walking mode, the user continuously presses the "set" button 144 of the input device 140 over an eighth predetermined time period or longer. The eighth predetermined time 15 period is, for example, 3 seconds, which is similar to the third predetermined time period. Accordingly, the assistance apparatus 100 operates in the normal walking mode, as is illustrated in the flowchart in FIG. 24.

To select a mode other than the normal walking mode, the 20 user presses the "mode" button 143. Thus, the assistance apparatus 100 generates a tension in each wire in accordance with the generation pattern corresponding to the object transport walking mode to clarify the object transport walking mode. When the "set" button 144 is pressed over the 25 eighth predetermined time period or longer, the assistance apparatus 100 operates in the object transport walking mode. When the "mode" button 143 is pressed, the assistance apparatus 100 generates a tension in each wire in accordance with the generation pattern corresponding to the lifting mode 30 to clarify the lifting mode. Further, when the "set" button 144 is pressed over the eighth predetermined time period or longer, the assistance apparatus 100 operates in the lifting mode. When the "mode" button 143 is pressed, the assistance apparatus 100 generates a tension in each wire in 35 accordance with the generation pattern corresponding to the calibration mode to clarify the calibration mode. Further, when the "set" button 144 is pressed over the eighth predetermined time period or longer, the assistance apparatus 100 operates in the calibration mode. When the "mode" button 143 is pressed, the assistance apparatus 100 again clarifies the normal walking mode.

Accordingly, in the operation selection mode, the assistance apparatus 100 sequentially changes the operation mode to be clarified upon pressing the "mode" button 143, 40 and operates in the currently clarified operation mode upon pressing the "set" button 144. The order in which the operation modes are clarified is not limited to that described above, and the operation modes may be clarified in any order. The user may perform input in the operation selection 45 mode by using the terminal device 150, which is external to the assistance apparatus 100.

The operation of the assistance apparatus 100 for clarifying each operation mode and determining implementation of the operation mode will be described in further detail. 50 First, to clarify the normal walking mode, the drive control unit 122 generates a tension in each of the wires 110 in accordance with a generation pattern similar to the input profiles of the wire tensions illustrated in FIG. 25 for assisting normal walking of a user. Specifically, as illustrated in FIG. 29A, the drive control unit 122 alternately performs generation of a ninth tension in the pair of wires 110a2 and 110a3 and generation of the ninth tension in the pair of wires 55

110a1 and **110a4** at intervals of a ninth predetermined time period. The drive control unit **122** continuously generates the tension in the wires **110a2** and **110a3** over the ninth predetermined time period at the same timing and continuously generates the tension in the wires **110a1** and **110a4** over the ninth predetermined time period at the same timing. An interval of the ninth predetermined time period, for example, may be provided between the durations of generation of the tension in the two pairs. FIG. 29A is a diagram illustrating an example operation of the assistance apparatus **100** for clarifying the normal walking mode. In FIG. 29A, during the generation of the ninth tension in each of the wires **110a2** and **110a3**, the drive control unit **122** may not generate any tension in the wires **110a1** and **110a4**. In FIG. 29A, during the generation of the ninth tension in each of the wires **110a1** and **110a4**, the drive control unit **122** may not generate any tension in the wires **110a2** and **110a3**.

The ninth predetermined time period is, for example, 1 second, which is similar to the second predetermined time period. The ninth tension is greater than or equal to a third threshold value and is less than a tenth tension described below. The third threshold value is preferably a relatively small value that allows the user to clearly recognize a tension generated in a wire when the user is aware of the wire, but that keeps the load on the user low, and may be equal to the eighth threshold value. The third threshold value is preferably larger than the second threshold value and smaller than the first threshold value. The third threshold value is a value given by an expression of maximum tension $\times 0.2$ or is 20 N, for example. The ninth tension is, for example, a tension greater than or equal to 20 N and less than or equal to 30 N, which is similar to the second tension.

When the “set” button **144** of the input device **140** is pressed over the eighth predetermined time period or longer during the clarification of the normal walking mode, the drive control unit **122** clarifies determination that the normal walking mode is to be implemented, and then starts an operation in the normal walking mode. To clarify determination that the normal walking mode is to be implemented, as illustrated in FIG. 29B, the drive control unit **122** continuously generates a tenth tension in the pair of wires **110a2** and **110a3** over a tenth predetermined time period at the same timing, and thereafter continuously generates the tenth tension in the pair of wires **110a1** and **110a4** over the tenth predetermined time period at the same timing. An interval may be provided between the durations of generation of the tension in the two pairs. FIG. 29B is a diagram illustrating an example operation of the assistance apparatus **100** for clarifying determination that the normal walking mode is to be implemented. In FIG. 29B, during the generation of the tenth tension in each of the wires **110a2** and **110a3**, the drive control unit **122** may not generate any tension in the wires **110a1** and **110a4**. In FIG. 29B, during the generation of the tenth tension in each of the wires **110a1** and **110a4**, the drive control unit **122** may not generate any tension in the wires **110a2** and **110a3**.

The tenth predetermined time period is longer than the ninth predetermined time period. The tenth predetermined time period is, for example, 3 seconds, which is similar to the first predetermined time period. The tenth tension is greater than the ninth tension and is greater than or equal to a fourth threshold value and less than or equal to the maximum tension of a wire. The fourth threshold value is preferably a relatively large value that allows the user to clearly recognize a tension generated in a wire without awareness of the wire and may be equal to the seventh threshold value. The fourth threshold value is larger than the

third threshold value. The fourth threshold value is a value given by an expression of maximum tension $\times 0.4$ or is 40 N, for example. The tenth tension is, for example, a tension greater than or equal to 40 N and less than or equal to 100 N, which is similar to the first tension.

To clarify the object transport walking mode, the drive control unit **122** generates a tension in each of the wires **110** in accordance with a generation pattern similar to the input profiles of the wire tensions illustrated in FIG. 26 for assisting a user in walking while carrying an object. Specifically, as illustrated in FIG. 30A, the drive control unit **122** repeatedly performs generation of the ninth tension in the pair of wires **110a2** and **110a4**, generation of the ninth tension in the pair of wires **110a2** and **110a3**, and generation of the ninth tension in the pair of wires **110a1** and **110a4** in this order at intervals of the ninth predetermined time period. As in the normal walking mode, the tension is continuously generated in the wires in each pair over the ninth predetermined time period at the same timing. An interval of the ninth predetermined time period, for example, may be provided between the durations of generation of the tension in the three pairs. FIG. 30A is a diagram illustrating an example operation of the assistance apparatus **100** for clarifying the object transport walking mode. In FIG. 30A, during the generation of the ninth tension in each wire included in the pair of wires **110a2** and **110a4**, the drive control unit **122** may not generate any tension in the wires **110a1** and **110a3**. In FIG. 30A, during the generation of the ninth tension in each wire included in the pair of wires **110a2** and **110a3**, the drive control unit **122** may not generate any tension in the wires **110a1** and **110a4**. In FIG. 30A, during the generation of the ninth tension in each wire included in the pair of wires **110a1** and **110a4**, the drive control unit **122** may not generate any tension in the wires **110a2** and **110a3**.

When the “set” button **144** of the input device **140** is pressed over the eighth predetermined time period or longer during the clarification of the object transport walking mode, the drive control unit **122** clarifies determination that the object transport walking mode is to be implemented, and then starts an operation in the object transport walking mode. To clarify determination that the object transport walking mode is to be implemented, as illustrated in FIG. 30B, the drive control unit **122** continuously generates the tenth tension in the pair of wires **110a2** and **110a4**, the pair of wires **110a2** and **110a3**, and the pair of wires **110a1** and **110a4** in this order over the tenth predetermined time period at the same timing for the wires in each pair. An interval may be provided between the durations of generation of the tension in the three pairs. FIG. 30B is a diagram illustrating an example operation of the assistance apparatus **100** for clarifying determination that the object transport walking mode is to be implemented. In FIG. 30B, during the generation of the tenth tension in each wire included in the pair of wires **110a2** and **110a4**, the drive control unit **122** may not generate any tension in the wires **110a1** and **110a3**. In FIG. 30B, during the generation of the tenth tension in each wire included in the pair of wires **110a2** and **110a3**, the drive control unit **122** may not generate any tension in the wires **110a1** and **110a4**. In FIG. 30B, during the generation of the tenth tension in each wire included in the pair of wires **110a1** and **110a4**, the drive control unit **122** may not generate any tension in the wires **110a2** and **110a3**.

To clarify the lifting mode, the drive control unit **122** generates a tension in each wire in accordance with a generation pattern similar to the input profiles of the wire tensions illustrated in FIG. 27 for assisting the user in performing a lifting motion. Specifically, as illustrated in

FIG. 31A, the drive control unit 122 repeatedly performs generation of the ninth tension in the pair of wires 110a2 and 110a4 at intervals of the ninth predetermined time period. As in the normal walking mode, the tension is continuously generated in the wires 110a2 and 110a4 over the ninth predetermined time period at the same timing. An interval of the ninth predetermined time period, for example, may be provided between the durations of generation of the tension. FIG. 31A is a diagram illustrating an example operation of the assistance apparatus 100 for clarifying the lifting mode. In FIG. 31A, during the generation of the ninth tension in each of the wires 110a2 and 110a4, the drive control unit 122 may not generate any tension in the wires 110a1 and 110a3.

When the “set” button 144 of the input device 140 is pressed over the eighth predetermined time period or longer during the clarification of the lifting mode, the drive control unit 122 clarifies determination that the lifting mode is to be implemented, and then starts an operation in the lifting mode. To clarify determination that the lifting mode is to be implemented, as illustrated in FIG. 31B, the drive control unit 122 continuously generates the tenth tension in the wires 110a2 and 110a4 over the tenth predetermined time period at the same timing. FIG. 31B is a diagram illustrating an example operation of the assistance apparatus 100 for clarifying determination that the lifting mode is to be implemented. In FIG. 31B, during the generation of the tenth tension in each of the wires 110a2 and 110a4, the drive control unit 122 may not generate any tension in the wires 110a1 and 110a3.

To clarify the calibration mode, the drive control unit 122 sequentially generates tensions in all the wires 110. Specifically, as illustrated in FIG. 32A, the drive control unit 122 repeatedly performs generation of the ninth tension in the wire 110a2, generation of the ninth tension in the wire 110a4, generation of the ninth tension in the wire 110a3, and generation of the ninth tension in the wire 110a1 in this order at intervals of the ninth predetermined time period. The tension is continuously generated in each of the wires 110 over the ninth predetermined time period. An interval of the ninth predetermined time period, for example, may be provided between the durations of generation of the tension. FIG. 32A is a diagram illustrating an example operation of the assistance apparatus 100 for clarifying the calibration mode. In FIG. 32A, during the generation of the ninth tension in the wire 110a1, the drive control unit 122 may not generate any tension in the wire 110a2, 110a3, and 110a4. In FIG. 32A, during the generation of the ninth tension in the wire 110a2, the drive control unit 122 may not generate any tension in the wire 110a1, 110a3, and 110a4. In FIG. 32A, during the generation of the ninth tension in the wire 110a3, the drive control unit 122 may not generate any tension in the wire 110a1, 110a2, and 110a4. In FIG. 32A, during the generation of the ninth tension in the wire 110a4, the drive control unit 122 may not generate any tension in the wires 110a1, 110a2, and 110a3.

When the “set” button 144 of the input device 140 is pressed over the eighth predetermined time period or longer during the clarification of the calibration mode, the drive control unit 122 clarifies determination that the calibration mode is to be implemented, and then starts an operation in the calibration mode. To clarify determination that the calibration mode is to be implemented, as illustrated in FIG. 32B, the drive control unit 122 continuously generates the tenth tension in each of the wire 110a2, the wire 110a4, the wire 110a3, and the wire 110a1 in this order over the tenth predetermined time period. An interval may be provided between the durations of generation of the tension in the four

wires 110a1 to 110a4. FIG. 32B is a diagram illustrating an example operation of the assistance apparatus 100 for clarifying determination that the calibration mode is to be implemented. In FIG. 32B, during the generation of the tenth tension in the wire 110a1, the drive control unit 122 may not generate any tension in the wire 110a2, 110a3, and 110a4. In FIG. 32B, during the generation of the tenth tension in the wire 110a2, the drive control unit 122 may not generate any tension in the wire 110a1, 110a3, and 110a4. In FIG. 32B, during the generation of the tenth tension in the wire 110a3, the drive control unit 122 may not generate any tension in the wire 110a1, 110a2, and 110a4. In FIG. 32B, during the generation of the tenth tension in the wire 110a4, the drive control unit 122 may not generate any tension in the wires 110a1, 110a2, and 110a3.

In the foregoing description, the assistance apparatus 100 switches between the operation modes to be clarified and determines that an operation mode is to be implemented through input to the input device 140 or the terminal device 150. However, this embodiment is not limited to this operation. For example, the user may pull a wire. For example, the drive control unit 122 may identify pulling one or more wires with a predetermined tension or higher and/or pulling one or more wires in a predetermined pattern or at a predetermined timing as being identical to pressing the “mode” button 143 of the input device 140. For example, when the wires 110a1 and 110a3 are simultaneously pulled once with a predetermined tension or higher, the drive control unit 122 may identify this operation as being identical to pressing the “mode” button 143. Further, the drive control unit 122 may identify pulling one or more wires with a predetermined tension or higher and/or pulling one or more wires in a predetermined pattern or at a predetermined timing by using a method different from that described above as being identical to pressing the “set” button 144 of the input device 140. For example, when the wires 110a1 and 110a3 are simultaneously pulled twice with a predetermined tension or higher, the drive control unit 122 may identify this operation as being identical to pressing the “set” button 144.

Furthermore, the assistance apparatus 100 switches between the operation modes to be clarified when the “mode” button 143 of the input device 140 is pressed. However, this embodiment is not limited to this operation. For example, when a certain operation mode is clarified and then the user does not input an instruction for selecting the operation mode after the lapse of a predetermined time, the assistance apparatus 100 may clarify another operation mode. The assistance apparatus 100 may sequentially clarify the four operation modes at intervals of a predetermined time period until any instruction is received from the user.

When clarifying each operation mode and when notifying the user of determination that each operation mode is to be implemented, the assistance apparatus 100 may drive the motors 114 by using methods different from one operation mode to another. Specifically, the timing and pattern of driving the motors 114 may differ from one operation mode to another. For example, to generate a tension in each wire over a period of 1 second, the drive control unit 122 may intermittently drive the corresponding one of the motors 114 or may make the pattern of intermittently driving corresponding one of the motors 114 different from one operation mode to another. For example, the time period during which each motor is driven once may differ from one operation mode to another, and therefore the number of times each motor is driven over a period of 1 second may differ from

one operation mode to another. This allows the user to identify an operation mode also from the sounds of driving the motors 114.

4. Example

An experiment was made for the assistance operation using the assistance apparatus 100 according to the embodiment in three patterns for comparison and verification. The operation in the first pattern, the operation in the second pattern, and an operation in a new fourth pattern were compared.

In the operation in the fourth pattern, the assistance apparatus 100 controlled wire tension for the wires 110a1 and 110a3 in a way similar to that for the operation in the first pattern and the operation in the second pattern. Further, the assistance apparatus 100 continuously generated a maximum tension in the wires 110a2 and 110a4 during the entire duration of the assistance. Thus, strong assistance forces for extension were continuously applied to both legs of the wearer of the assistance apparatus 100 all the time during the entire duration of the assistance.

In the operation in the second pattern, the tension to be generated in the wire 110a2 was set to 20% of the maximum tension during the sixth period in the gait phase of the left leg. Further, the tension to be generated in the wire 110a4 was set to 20% of the maximum tension during the eighth period in the gait phase of the right leg. The maximum tension to be generated in the wire 110 was set to 100 N in the operation in the first pattern, the operation in the second pattern, and the operation in the fourth pattern.

The experiment was conducted on four subjects, namely A to D. The subjects A, C, and D were males, and the subject B was female. All the subjects A to D wearing the assistance apparatus 100 received three types of assistance based on the operation in the first pattern, the operation in the second pattern, and the operation in the fourth pattern, while walking forward with luggage in both hands in front of the body. Then, the subjects A to D selected one optimum operation, which was the most comfortable walking operation, from among the operations in the three patterns. The selection results are given in Table 1 below. Table 1 indicates that the operation in the second pattern is the most effective to assist the wearer in walking forward while carrying luggage. Table 1 also indicates that the operation in the first pattern is also effective to assist the wearer in walking forward.

TABLE 1

Evaluation results of assistance based on operations in patterns			
Subject	First pattern	Second pattern	Fourth pattern
A		Optimum	
B		Optimum	
C		Optimum	
D	Optimum		

5. Other Embodiments

While an assistance apparatus and so on according to one or more aspects have been described in conjunction with an embodiment and a modification, the present disclosure is not limited to the embodiment and modification. Applications of various modifications conceived of by persons skilled in the art to this embodiment and modification and embodiments based on combinations of constituent elements in different embodiments and modifications may also be encompassed

in the scope of one or more aspects as long as such applications or embodiments do not depart from the gist of the present disclosure.

For example, in the assistance apparatuses 100 and 200 according to the embodiment and modification, the timings at which the control unit 120 activates the motors 114 to generate tensions in the wires 110 and values of the gait phase regarding the input profiles of the tensions are not limited to the values described in the embodiment and modification. The timings and the values of the gait phase regarding the input profiles of the tensions may be different from those described in the embodiment and modification. For example, an error of several percent in terms of gait phase may occur.

In the assistance apparatuses 100 and 200 according to the embodiment and modification, each of the wires 110 is provided with a motor. However, the present disclosure is not limited to the embodiment and modification. One motor may be coupled to wires. For example, in the assistance apparatus 200, one motor may pull the wires 110a1 and 110a5. That is, the assistance apparatus 200 may include, for example, four motors so that one motor is provided for two wires.

In the assistance apparatuses 100 and 200 according to the embodiment and the modification, four wires or eight wires are used to couple the upper-body belt 111 to the knee belts 112a and 112b. That is, two wires or four wires are coupled to each knee belt. However, the number of wires to be coupled to each knee belt is not limited to that described above. Any number of wires more than one may be coupled to each knee belt. For example, the numbers of wires to be coupled to the front part and the back part of each knee belt may be different. Flexion of the left leg may mean flexion of the hip joint of the left leg. Flexion of the right leg may mean flexion of the hip joint of the right leg. Extension of the left leg may mean extension of the hip joint of the left leg. Extension of the right leg may mean extension of the hip joint of the right leg.

The present disclosure is applicable to an apparatus for assisting a user in changing direction.

What is claimed is:

1. An assistance apparatus comprising:
an upper-body belt adapted to be worn on an upper half of a body of a user;
a left knee belt adapted to be worn on a left knee of the user;
a right knee belt adapted to be worn on a right knee of the user;
a first wire that couples the upper-body belt and the left knee belt to each other on or above a front part of the body of the user;
a second wire that couples the upper-body belt and the left knee belt to each other on or above a back part of the body of the user;
a third wire that couples the upper-body belt and the right knee belt to each other on or above the front part of the body of the user;
a fourth wire that couples the upper-body belt and the right knee belt to each other on or above the back part of the body of the user;
four motors including a first motor, a second motor, a third motor and a fourth motor;
a walk timing detecting unit; and
a control circuit, wherein
in first assistance for assisting the user in walking while carrying an object,

61

- (i) the first motor generates a tension greater than or equal to a first threshold value in the first wire during a first period, the first period being a period of 35% or more and 90% or less of a gait phase of a left leg of the user,
- (ii) the second motor generates a tension greater than or equal to the first threshold value in the second wire during a second period, the second period being from a point in a range of 65% or more and less than 100% of the gait phase of the left leg to a point in a range of 0% or more and 25% or less of a subsequent gait phase of the left leg,
- (iii) the third motor generates a tension greater than or equal to the first threshold value in the third wire during a third period, the third period being a period of 35% or more and 90% or less of a gait phase of a right leg of the user,
- (iv) the fourth motor generates a tension greater than or equal to the first threshold value in the fourth wire during a fourth period, the fourth period being from a point in a range of 65% or more and less than 100% of the gait phase of the right leg to a point in a range of 0% or more and 25% or less of a subsequent gait phase of the right leg,
- (v) the first motor generates a tension less than a second threshold value in the first wire during a fifth period, the fifth period being from a point in a range of more than 90% and less than 100% of the gait phase of the left leg to a point in a range of 0% or more and less than 35% of the subsequent gait phase of the left leg,
- (vi) the second motor generates a tension greater than or equal to the second threshold value in the second wire during a sixth period, the sixth period being a period of more than 25% and less than 65% of the gait phase of the left leg,
- (vii) the third motor generates a tension less than the second threshold value in the third wire during a seventh period, the seventh period being from a point in a range of more than 90% and less than 100% of the gait phase of right leg to a point in a range of 0% or more and less than 35% of the subsequent gait phase of the right leg, and
- (viii) the fourth motor generates a tension greater than or equal to the second threshold value in the fourth wire during an eighth period, the eighth period being a period of more than 25% and less than 65% of the gait phase of the right leg,

before an implementation of the first assistance is determined,
 the four motors execute operations (a1), (a2) and (a3) of promoting the implementation of the first assistance, in the operation (a1), the second motor and the fourth motor respectively generate a tension greater than or equal to a third threshold value in the second wire and the fourth wire,
 in the operation (a2), the second motor and the third motor respectively generate a tension greater than or equal to the third threshold value in the second wire and the third wire,
 in the operation (a3), the first motor and the fourth motor respectively generate a tension greater than or equal to the third threshold value in the first wire and the fourth wire,
 when the control circuit receives, during execution of the operations (a1), (a2) and (a3), determination that the first assistance is to be implemented,

62

before the first assistance is implemented, the four motors execute operations (a4), (a5) and (a6) indicating that the implementation of the first assistance is determined, in the operation (a4), the second motor and the fourth motor respectively generate a tension greater than or equal to a fourth threshold value in the second wire and the fourth wire,

in the operation (a5), the second motor and the third motor respectively generate a tension greater than or equal to the fourth threshold value in the second wire and the third wire,

in the operation (a6), the first motor and the fourth motor respectively generate a tension greater than or equal to the fourth threshold value in the first wire and the fourth wire,

the first threshold value is larger than the second threshold value,

the fourth threshold value is larger than the third threshold value, and

the walk timing detecting unit determines each percentage of the gait phase of the left leg and each percentage of the gait phase of the right leg based on information obtained using a sensor.

2. The assistance apparatus according to claim 1, wherein the left leg shifts from a stance phase to a swing phase during the first period,

the left leg shifts from the swing phase to the stance phase during the second period,

the right leg shifts from the stance phase to the swing phase during the third period, and

the right leg shifts from the swing phase to the stance phase during the fourth period.

3. The assistance apparatus according to claim 1, wherein in the first assistance,

the tension of the first wire in the fifth period is less than the tension of the second wire in the sixth period, and the tension of the third wire in the seventh period is less than the tension of the fourth wire in the eighth period.

4. The assistance apparatus according to claim 1, wherein in second assistance for assisting the user in walking while carrying no object,

(i) the first motor generates a tension less than the second threshold value in the first wire during the fifth period,

(ii) the second motor generates a tension less than the second threshold value in the second wire during the sixth period,

(iii) the third motor generates a tension less than the second threshold value in the third wire during the seventh period, and

(iv) the fourth motor generates a tension less than the second threshold value in the fourth wire during the eighth period,

the tension of the second wire in the sixth period during the second assistance is less than the tension of the second wire in the sixth period during the first assistance,

the tension of the fourth wire in the eighth period during the second assistance is less than the tension of the fourth wire in the eighth period during the first assistance,

before an implementation of the second assistance is determined,

the four motors execute operations (b1) and (b2) of promoting the implementation of the second assistance,

63

in the operation (b1), the second motor and the third motor respectively generate a tension greater than or equal to the third threshold value in the second wire and the third wire,

in the operation (b2), the first motor and the fourth motor respectively generate a tension greater than or equal to the third threshold value in the first wire and the fourth wire,

when the control circuit receives, during execution of the operations (b1) and (b2), determination that the second assistance is to be implemented,

before the second assistance is implemented, the four motors execute operations (b3) and (b4) indicating that the implementation of the second assistance is determined,

in the operation (b3), the second motor and the third motor respectively generate a tension greater than or equal to the fourth threshold value in the second wire and the third wire, and

in the operation (b4), the first motor and the fourth motor respectively generate a tension greater than or equal to the fourth threshold value in the first wire and the fourth wire.

5. The assistance apparatus according to claim 1, wherein in second assistance for assisting the user in lifting an object,

the second motor and the fourth motor respectively generate a tension greater than a fifth threshold value in the second wire and the fourth wire,

the fifth threshold value is larger than the first threshold value and the second threshold value,

before an implementation of the second assistance is determined,

the second motor and the fourth motor execute an operation (b1) of promoting the implementation of the second assistance,

in the operation (b1), the second motor and the fourth motor respectively generate a tension greater than or equal to the third threshold value in the second wire and the fourth wire,

when the control circuit receives, during execution of the operation (b1), determination that the second assistance is to be implemented,

before the second assistance is implemented, the second motor and the fourth motor execute an operation (b2) indicating that the implementation of the second assistance is determined, and

in the operation (b2), the second motor and the fourth motor respectively generate a tension greater than or equal to the fourth threshold value in the second wire and the fourth wire.

6. The assistance apparatus according to claim 1, wherein the first wire has a first end fixed to the left knee belt, the first wire has a second end fixed to the first motor, the second wire has a first end fixed to the left knee belt, the second wire has a second end fixed to the second motor,

the third wire has a first end fixed to the right knee belt, the third wire has a second end fixed to the third motor, the fourth wire has a first end fixed to the right knee belt, and

the fourth wire has a second end fixed to the fourth motor.

7. The assistance apparatus according to claim 1, further comprising:

an additional four motors including a fifth motor, a sixth motor, a seventh motor and an eighth motor;

64

a fifth wire that couples the upper-body belt and the left knee belt to each other and that extends on or above the front part of the body of the user in a direction crossing a direction in which the first wire extends;

a sixth wire that couples the upper-body belt and the left knee belt to each other and that extends on or above the back part of the body of the user in a direction crossing a direction in which the second wire extends;

a seventh wire that couples the upper-body belt and the right knee belt to each other and that extends on or above the front part of the body of the user in a direction crossing a direction in which the third wire extends; and

an eighth wire that couples the upper-body belt and the right knee belt to each other and that extends on or above the back part of the body of the user in a direction crossing a direction in which the fourth wire extends, wherein

in the first assistance,

(i) the first motor and the fifth motor respectively generate a tension greater than or equal to the first threshold value in the first wire and the fifth wire during the first period,

(ii) the second motor and the sixth motor respectively generate a tension greater than or equal to the first threshold value in the second wire and the sixth wire during the second period,

(iii) the third motor and the seventh motor respectively generate a tension greater than or equal to the first threshold value in the third wire and the seventh wire during the third period,

(iv) the fourth motor and the eighth motor respectively generate a tension greater than or equal to the first threshold value in the fourth wire and the eighth wire during the fourth period,

(v) the first motor and the fifth motor respectively generate a tension less than the second threshold value in the first wire and the fifth wire during the fifth period,

(vi) the second motor and the sixth motor respectively generate a tension greater than or equal to the second threshold value in the second wire and the sixth wire during the sixth period,

(vii) the third motor and the seventh motor respectively generate a tension less than the second threshold value in the third wire and the seventh wire during the seventh period, and

(viii) the fourth motor and the eighth motor respectively generate a tension greater than or equal to the second threshold value in the fourth wire and the eighth wire during the eighth period.

8. The assistance apparatus according to claim 1, wherein a time point of 50% of the gait phase of the left leg determined by the walk timing detecting unit based on the information obtained using the sensor corresponds to a time point of 0% of the gait phase of the right leg determined by the walk timing detecting unit, and a time point of 50% of the gait phase of the right leg determined by the walk timing detecting unit based on the information obtained using the sensor corresponds to a time point of 0% of the gait phase of the left leg determined by the walk timing detecting unit.

9. The assistance apparatus according to claim 1, further comprising

a memory, wherein

the memory stores a program for controlling the four motors, and

65

the control circuit controls the four motors in accordance with the program.

10. The assistance apparatus according to claim 1, further comprising

the sensor that detects a gait cycle of the user, wherein the control circuit calculates the gait phase of the left leg and the gait phase of the right leg based on a sensor value of the sensor.

11. The assistance apparatus according to claim 5, wherein

in third assistance for assisting the user in walking while carrying no object,

(i) the first motor generates a tension less than the second threshold value in the first wire during the 15 fifth period,

(ii) the second motor generates a tension less than the second threshold value in the second wire during the 16 sixth period,

(iii) the third motor generates a tension less than the second threshold value in the third wire during the 20 seventh period, and

(iv) the fourth motor generates a tension less than the second threshold value in the fourth wire during the 25 eighth period,

the tension of the second wire in the sixth period during the third assistance is less than the tension of the second wire in the sixth period during the first assistance, the tension of the fourth wire in the eighth period during the third assistance is less than the tension of the fourth wire in the eighth period during the first assistance, before an implementation of the third assistance is determined,

35 the four motors execute operations (c1) and (c2) of promoting the implementation of the third assistance, in the operation (c1), the second motor and the third motor respectively generate a tension greater than or equal to the third threshold value in the second wire and the third wire,

40 in the operation (c2), the first motor and the fourth motor respectively generate a tension greater than or equal to the third threshold value in the first wire and the fourth wire,

45 when the control circuit receives, during execution of the operations (c1) and (c2), determination that the third assistance is to be implemented,

50 before the third assistance is implemented, the four motors execute operations (c3) and (c4) indicating that the implementation of the third assistance is determined,

55 in the operation (c3), the second motor and the third motor respectively generate a tension greater than or equal to the fourth threshold value in the second wire and the third wire,

in the operation (c4), the first motor and the fourth motor respectively generate a tension greater than or equal to the fourth threshold value in the first wire and the fourth wire,

60 the assistance apparatus further comprises an interface device,

the control circuit accepts selection of an assistance method including at least one of the first assistance, the second assistance, or the third assistance via the interface device, and

65 the control circuit controls the four motors in accordance with the accepted assistance method.

66

12. An assistance method for assisting a movement of a user by using wires attached to a body of the user, the assistance method comprising:

coupling, using a first wire among the wires, an upper-body belt and a left knee belt to each other on or above a front part of the body of the user, the upper-body belt being a belt adapted to be worn on an upper half of the body of the user, the left knee belt being a belt adapted to be worn on a left knee of the user;

coupling, using a second wire among the wires, the upper-body belt and the left knee belt to each other on or above a back part of the body of the user;

coupling, using a third wire among the wires, the upper-body belt and a right knee belt to each other on or above the front part of the body of the user, the right knee belt being a belt adapted to be worn on a right knee of the user;

coupling, using a fourth wire among the wires, the upper-body belt and the right knee belt to each other on or above the back part of the body of the user;

in first assistance for assisting the user in walking while carrying an object,

generating a tension greater than or equal to a first threshold value in the first wire during a first period, the first period being a period of 35% or more and 90% or less of a gait phase of a left leg of the user;

generating a tension greater than or equal to the first threshold value in the second wire during a second period, the second period being from a point in a range of 65% or more and less than 100% of the gait phase of the left leg to a point in a range of 0% or more and 25% or less of a subsequent gait phase of the left leg;

generating a tension greater than or equal to the first threshold value in the third wire during a third period, the third period being a period of 35% or more and 90% or less of a gait phase of a right leg of the user;

generating a tension greater than or equal to the first threshold value in the fourth wire during a fourth period, the fourth period being from a point in a range of 65% or more and less than 100% of the gait phase of the right leg to a point in a range of 0% or more and 25% or less of a subsequent gait phase of the right leg;

generating a tension less than a second threshold value in the first wire during a fifth period, the fifth period being from a point in a range of more than 90% and less than 100% of the gait phase of the left leg to a point in a range of 0% or more and less than 35% of the subsequent gait phase of the left leg;

generating a tension greater than or equal to the second threshold value in the second wire during a sixth period, the sixth period being a period of more than 25% and less than 65% of the gait phase of the left leg;

generating a tension less than the second threshold value in the third wire during a seventh period, the seventh period being from a point in a range of more than 90% and less than 100% of the gait phase of right leg to a point in a range of 0% or more and less than 35% of the subsequent gait phase of the right leg;

generating a tension greater than or equal to the second threshold value in the fourth wire during an eighth period, the eighth period being a period of more than 25% and less than 65% of the gait phase of the right leg; before determining that the first assistance is to be implemented,

executing operations (a1), (a2) and (a3) of promoting an implementation of the first assistance;

67

in the operation (a1), generating a tension greater than or equal to a third threshold value in the second wire and the fourth wire;

in the operation (a2), generating a tension greater than or equal to the third threshold value in the second wire and the third wire;

in the operation (a3), generating a tension greater than or equal to the third threshold value in the first wire and the fourth wire;

when receiving, during execution of the operations (a1), (a2) and (a3), determination that the first assistance is to be implemented,

before the implementation of the first assistance, executing operations (a4), (a5) and (a6) indicating that the implementation of the first assistance is determined;

in the operation (a4), generating a tension greater than or equal to a fourth threshold value in the second wire and the fourth wire;

in the operation (a5), generating a tension greater than or equal to the fourth threshold value in the second wire and the third wire; and

in the operation (a6), generating a tension greater than or equal to the fourth threshold value in the first wire and the fourth wire, wherein

the first threshold value is larger than the second threshold value,

the fourth threshold value is larger than the third threshold value,

the tension of the first wire, the tension of the second wire, the tension of the third wire, and the tension of the fourth wire are generated and adjusted by four motors that are controlled by at least one control circuit, and each percentage of the gait phase of the left leg and each percentage of the gait phase of the right leg is determined by a walk timing detecting unit based on information obtained using a sensor.

13. The assistance method according to claim 12, wherein the left leg shifts from a stance phase to a swing phase during the first period,

the left leg shifts from the swing phase to the stance phase during the second period,

the right leg shifts from the stance phase to the swing phase during the third period, and

the right leg shifts from the swing phase to the stance phase during the fourth period.

14. The assistance method according to claim 12, wherein in the first assistance, the tension of the first wire in the fifth period is less than the tension of the second wire in the sixth period, and the tension of the third wire in the seventh period is less than the tension of the fourth wire in the eighth period.

15. The assistance method according to claim 12, further comprising:

in second assistance for assisting the user in walking while carrying no object,

generating a tension less than the second threshold value in the first wire during the fifth period;

generating a tension less than the second threshold value in the second wire during the sixth period;

generating a tension less than the second threshold value in the third wire during the seventh period;

generating a tension less than the second threshold value in the fourth wire during the eighth period,

the tension of the second wire in the sixth period during the second assistance being less than the tension of the second wire in the sixth period during the first assistance,

68

the tension of the fourth wire in the eighth period during the second assistance being less than the tension of the fourth wire in the eighth period during the first assistance;

before determining that the second assistance is to be implemented,

executing operations (b1) and (b2) of promoting an implementation of the second assistance;

in the operation (b1), generating a tension greater than or equal to the third threshold value in the second wire and the third wire;

in the operation (b2), generating a tension greater than or equal to the third threshold value in the first wire and the fourth wire;

when receiving, during execution of the operations (b1) and (b2), determination that the second assistance is to be implemented,

before the implementation of the second assistance, executing operations (b3) and (b4) indicating that the implementation of the second assistance is determined;

in the operation (b3), generating a tension greater than or equal to the fourth threshold value in the second wire and the third wire; and

in the operation (b4), generating a tension greater than or equal to the fourth threshold value in the first wire and the fourth wire.

16. The assistance method according to claim 12, further comprising:

in second assistance for assisting the user in lifting an object,

generating a tension greater than a fifth threshold value in the second wire and the fourth wire,

the fifth threshold value being larger than the first threshold value and the second threshold value;

before determining that the second assistance is to be implemented,

executing an operation (b1) of promoting an implementation of the second assistance;

in the operation (b1), generating a tension greater than or equal to the third threshold value in the second wire and the fourth wire;

when receiving, during execution of the operation (b1), determination that the second assistance is to be implemented,

before the implementation of the second assistance, executing an operation (b2) indicating that the implementation of the second assistance is determined; and

in the operation (b2), generating a tension greater than or equal to the fourth threshold value in the second wire and the fourth wire.

17. The assistance method according to claim 12, wherein a first end of the first wire is fixed to the left knee belt, a second end of the first wire is fixed to a first motor of the four motors,

a first end of the second wire is fixed to the left knee belt, a second end of the second wire is fixed to a second motor of the four motors,

a first end of the third wire is fixed to the right knee belt, a second end of the third wire is fixed to a third motor of the four motors,

a first end of the fourth wire is fixed to the right knee belt, and

a second end of the fourth wire is fixed to a fourth motor of the four motors.

69

18. The assistance method according to claim 12, further comprising:

coupling, using a fifth wire among the wires, the upper-body belt and the left knee belt to each other, the fifth wire extending on or above the front part of the body of the user in a direction crossing a direction in which the first wire extends;
 coupling, using a sixth wire among the wires, the upper-body belt and the left knee belt to each other, the sixth wire extending on or above the back part of the body of the user in a direction crossing a direction in which the second wire extends;
 coupling, using a seventh wire among the wires, the upper-body belt and the right knee belt to each other, the seventh wire extending on or above the front part of the body of the user in a direction crossing a direction in which the third wire extends;
 coupling, using an eighth wire among the wires, the upper-body belt and the right knee belt to each other, the eighth wire extending on or above the back part of the body of the user in a direction crossing a direction in which the fourth wire extends;
 in the first assistance,
 generating a tension greater than or equal to the first threshold value in the first wire and the fifth wire during the first period;
 generating a tension greater than or equal to the first threshold value in the second wire and the sixth wire during the second period;
 generating a tension greater than or equal to the first threshold value in the third wire and the seventh wire during the third period;
 generating a tension greater than or equal to the first threshold value in the fourth wire and the eighth wire during the fourth period;
 generating a tension less than the second threshold value in the first wire and the fifth wire during the fifth period;
 generating a tension greater than or equal to the second threshold value in the second wire and the sixth wire during the sixth period;
 generating a tension less than the second threshold value in the third wire and the seventh wire during the seventh period; and
 generating a tension greater than or equal to the second threshold value in the fourth wire and the eighth wire during the eighth period,
 wherein the tension of the fifth wire, the tension of the sixth wire, the tension of the seventh wire, and the tension of the eighth wire are generated and adjusted by four additional motors that are controlled by the at least one control circuit.

19. The assistance method according to claim 12, wherein a time point of 50% of the gait phase of the left leg determined by the walk timing detecting unit based on the information obtained using the sensor corresponds to a time point of 0% of the gait phase of the right leg determined by the walk timing detecting unit, and a time point of 50% of the gait phase of the right leg determined by the walk timing detecting unit based on the information obtained using the sensor corresponds to a time point of 0% of the gait phase of the left leg determined by the walk timing detecting unit.

20. The assistance method according to claim 12, further comprising:

acquiring a sensor value of the sensor that detects a gait cycle of the user; and

70

calculating the gait phase of the left leg and the gait phase of the right leg based on the sensor value.

21. The assistance method according to claim 16, further comprising:

in third assistance for assisting the user in walking while carrying no object,
 generating a tension less than the second threshold value in the first wire during the fifth period;
 generating a tension less than the second threshold value in the second wire during the sixth period;
 generating a tension less than the second threshold value in the third wire during the seventh period;
 generating a tension less than the second threshold value in the fourth wire during the eighth period,
 the tension of the second wire in the sixth period during the third assistance being less than the tension of the second wire in the sixth period during the first assistance,
 the tension of the fourth wire in the eighth period during the third assistance being less than the tension of the fourth wire in the eighth period during the first assistance;
 before determining that the third assistance is to be implemented,
 executing operations (c1) and (c2) of promoting an implementation of the third assistance;
 in the operation (c1), generating a tension greater than or equal to the third threshold value in the second wire and the third wire;
 in the operation (c2), generating a tension greater than or equal to the third threshold value in the first wire and the fourth wire;
 when receiving, during execution of the operations (c1) and (c2), determination that the third assistance is to be implemented,
 before the implementation of the third assistance, executing operations (c3) and (c4) indicating that the implementation of the third assistance is determined;
 in the operation (c3), generating a tension greater than or equal to the fourth threshold value in the second wire and the third wire;
 in the operation (c4), generating a tension greater than or equal to the fourth threshold value in the first wire and the fourth wire;
 accepting selection of an assistance method including at least one of the first assistance, the second assistance, or the third assistance via an interface device; and generating a tension in the first wire, the second wire, the third wire, and the fourth wire in accordance with the accepted assistance method.

22. A non-transitory computer readable recording medium storing a control program for causing an assist device including a processor to execute a process, the control program being used in the assist device including

a first wire coupling an upper-body belt and a left knee belt to each other on or above a front part of a body of a user, the upper-body belt being a belt adapted to be worn on an upper half of the body of the user, the left knee belt being a belt adapted to be worn on a left knee of the user,
 a second wire coupling the upper-body belt and the left knee belt to each other on or above a back part of the body of the user,
 a third wire coupling the upper-body belt and a right knee belt to each other on or above the front part of the body of the user, the right knee belt being a belt adapted to be worn on a right knee of the user,

71

a fourth wire coupling the upper-body belt and the right knee belt to each other on or above the back part of the body of the user;

the process comprising:

when assisting the user in walking while carrying an object,

causing a first motor to generate a tension greater than or equal to a first threshold value in the first wire during a first period, the first period being a period of 35% or more and 90% or less of a gait phase of a left leg of the user;

causing a second motor to generate a tension greater than or equal to the first threshold value in the second wire during a second period, the second period being from a point in a range of 65% or more and less than 100% of the gait phase of the left leg to a point in a range of 0% or more and 25% or less of a subsequent gait phase of the left leg;

causing a third motor to generate a tension greater than or equal to the first threshold value in the third wire during a third period, the third period being a period of 35% or more and 90% or less of a gait phase of a right leg of the user;

causing a fourth motor to generate a tension greater than or equal to the first threshold value in the fourth wire during a fourth period, the fourth period being from a point in a range of 65% or more and less than 100% of the gait phase of the right leg to a point in a range of 0% or more and 25% or less of a subsequent gait phase of the right leg;

causing the first motor to generate a tension less than a second threshold value in the first wire during a fifth period, the fifth period being from a point in a range of more than 90% and less than 100% of the gait phase of the left leg to a point in a range of 0% or more and less than 35% of the subsequent gait phase of the left leg;

causing the second motor to generate a tension greater than or equal to the second threshold value in the second wire during a sixth period, the sixth period being a period or more than 25% and less than 65% of the gait phase of the left leg;

causing the third motor to generate a tension less than the second threshold value in the third wire during a seventh period, the seventh period being from a point in a range of more than 90% and less than 100% of the gait phase of right leg to a point in a range of 0% or more and less than 35% of the subsequent gait phase of the right leg;

causing the fourth motor to generate a tension greater than or equal to the second threshold value in the fourth wire

72

during an eighth period, the eighth period being a period of more than 25% and less than 65% of the gait phase of the right leg;

before determining that the first assistance is to be implemented, causing the first motor, the second motor, the third motor and the fourth motor to execute operations (a1), (a2) and (a3) of promoting an implementation of the first assistance;

in the operation (a1), causing the second motor and the fourth motor to respectively generate a tension greater than or equal to a third threshold value in the second wire and the fourth wire;

in the operation (a2), causing the second motor and the third motor to respectively generate a tension greater than or equal to the third threshold value in the second wire and the third wire;

in the operation (a3), causing the first motor and the fourth motor to respectively generate a tension greater than or equal to the third threshold value in the first wire and the fourth wire;

when receiving, during execution of the operations (a1), (a2) and (a3), determination that the first assistance is to be implemented, before the implementation of the first assistance, causing the first motor, the second motor, the third motor and the fourth motor to execute operations (a4), (a5) and (a6) indicating that the implementation of the first assistance is determined;

in the operation (a4), causing the second motor and the fourth motor to respectively generate a tension greater than or equal to a fourth threshold value in the second wire and the fourth wire;

in the operation (a5), causing the second motor and the third motor to respectively generate a tension greater than or equal to the fourth threshold value in the second wire and the third wire; and

in the operation (a6), causing the first motor and the fourth motor to respectively generate a tension greater than or equal to the fourth threshold value in the first wire and the fourth wire, wherein

the first threshold value is larger than the second threshold value,

the fourth threshold value is larger than the third threshold value, and

each percentage of the gait phase of the left leg and each percentage of the gait phase of the right leg is determined by a walk timing detecting unit based on information obtained using a sensor.
